UNITED STATES PATENT OFFICE.

LUTHER C. CROWELL, OF BROOKLYN, ASSIGNOR TO ROBERT HOE, STEPHEN D. TUCKER, THEODORE H. MEAD, AND CHARLES W. CARPENTER, OF NEW YORK, N. Y.

NEWSPAPER FOLDING AND STAPLE-BINDING MACHINE.

SPECIFICATION forming part of Letters Patent No. 510,528, dated December 12, 1893.

Application filed February 28, 1893. Serial No. 464,007. (No model.)

To all whom it may concern:

Be it known that I, LUTHER C. CROWELL, a citizen of the United States, residing at the city of Brooklyn, county of Kings, and State 5 of New York, have invented certain new and useful Improvements in Newspaper Folding and Staple-Binding Machines, fully described and represented in the following specification and the accompanying drawings, forming a part of the same.

The principal object of this invention is to provide printing machines of that class which produce the component sheets or leaves of a book-like package, consisting of two or more 15 associated sheets, with a delivery mechanism having means for uniting webs or sheets by one or more staples set in, on, or near, the ultimate binding line thereof, whether the webs or sheets are of the same or varying 20 sizes, and folded or simply associated, and if folded, either before, after or during the folding operation, so that the product will be delivered as a pamphlet or book-like package the plies or leaves of which are securely bound 25 together so as to admit of their several plies or leaves being turned one upon the other without separation at their line of union. Ordinarily, this union of the various plies or sheets, constituting the leaves of a book-like 30 package or sheets composing a newspaper, are secured on their common binding line by paste which is applied during the movement of the paper through the machine, either in the web or as sheets, the paste either in lines 35 or separate spots, being applied along the appropriate line of ultimate folding which becomes the binding line of the book-like product.

Owing to the high rate of speed at which 40 printing machines are made to operate, difficulties exist in properly supplying paste to the running paper, and more especially is this the case where the line of paste is to be applied in a direction transverse to the run of 45 the paper; and, whether applied parallel with or transverse to the run of the paper, practice has demonstrated that in such transverse pasting, exact registration with the ultimate line of binding fold is not always certain, especially when the product is made by unit-

ing two or more sheets from different sources of printing, whence results an unevenly united product, and, in the other case or longitudinal pasting, it is found in practice that the paste either extends beyond the necessary line of union or extent of deposit required for binding purposes or is applied over too great a space laterally by direct action of the pasting devices, which, after a short run, accumulate a body of paste along and projecting laterally from their edges and thus become carriers depositing a wide line of paste upon the paper; or, the paste is spattered beyond the proper line or lines of deposit by the rapid rotative action of the pasting devices. 55 In both methods of pasting, as performed in rapidly operating machines, experience has shown that in order to form a binding line of sufficient adhesive strength, a somewhat heavy body or line of paste must be deposited 60 upon the material, and this becomes spread laterally when the plies are pressed closely together, in associating, folding or delivering them; and hence the plies or sheets become united in inappropriate places which frequently necessitates their being torn apart, 65 in order that the leaves composing the product may be separated and turned one over the other upon their binding line. Furthermore the transfer of paste from its fountain 70 through the applying device to the paper is not at all certain because of defective taking up at the high speed of fast printing machines whence frequently result many non-pasted 75 products; and while these defects are objectionable in newspaper work each becomes in the production of books or pamphlets a very 80 serious objection.

All of the disadvantages due to the use of paste as the means of uniting webs or sheets 85 of paper are avoided by uniting the plies thereof in, on, or near, their ultimate binding line by the use of staples passed through the plies of paper and bent or clinched so as to secure them in place. The present invention 90 obviates these defects by inserting and clinching staples at one or more points in, on, or near, the line of ultimate fold of the associated plies of paper, webs or sheets, as they are delivered from a rapidly operating machine, 95 100

such as a web printing machine in which the parts are rotative in action, without necessarily reducing the ordinary or fast speed of such machines, whereby the products thereof are 5 provided with a binding uniting their plies by means which constitute a strong, durable and permanent fastening, in one form strictly within the double or bight thereof, and in the other form accurately near and parallel with 10 the edge of such binding line.

Sheets of paper have heretofore been secured together by wire staples which have been inserted therein and clinched by means of stapling mechanisms, but the sheets of paper 15 are fed into those machines by hand, and, in attaining the position to be operated upon by the stapling devices, are always moved in a different direction from that in which the staple holding device is carried to the staple 20 inserting and clinching point; and, moreover, when the paper is fed into such position it remains in a state of rest, while the staple holding or presenting device is moved to present the staple thereto and while the 25 inserting and clinching operations are effected, the operations of feeding and stapling thus necessarily being intermittent and consequently slow. Such a stapling mechanism would not be suitable to or adequate for the 30 stapling of the product of a printing or other machine which delivers webs associated and sometimes folded longitudinally, or sheets associated, or sometimes sheets folded longitudinally and transversely, in large numbers 35 per minute, which webs or sheets necessarily run onward at a high rate of surface speed, and which speed cannot be greatly modified without impairing the efficiency of the machine. Any operation therefore, which necessitates the suspension of the feeding movement of the material, after it has reached a 40 position to be stapled, in which position it rests while the stapling devices are being moved into a like position to insert the staple 45 into the material and clinch its legs thereon, would not only prevent the stapling machine from operating at a high speed, but so limit the speed of an otherwise fast machine, such as is above referred to, as to inhibit the combination of such stapling mechanism with 50 its delivery.

Advantageous results in a high degree arise from the present invention, first in accomplishing the union of the plies of the 55 product delivered from a rapidly operating machine, as a fast printing machine, by binding them together with wire staples; and, second, in performing the operations of presenting, inserting and clinching staples in, 60 on, or near, the line of binding fold in the paper, or near and parallel with the binding edge of the plicated pack, without necessitating that the moving paper or material shall be, even momentarily, brought to a 65 state of rest while being delivered.

The said invention consists in the combination with means for feeding plicated ma-

terial onward past a staple inserting means, of a staple inserting means operating to insert a staple through the moving material. 70 It also includes in combination therewith, means for clinching the staple legs.

It also consists in staple holding and inserting devices of a stapling mechanism, one or both, mounted in traveling, preferably rotative, supports, together with means for feeding the material to be stapled past said devices in the direction of their travel, preferably onward with them so that the feeding movement of the material need not necessarily 75 be suspended, even momentarily, whereby a staple will be inserted in such material.

It also includes, in combination therewith, a staple leg clinching device, which may be stationary but preferably is mounted in a 80 like support.

It also embraces, in combination with the foregoing, mechanism for printing one or more webs or sheets upon one or both sides; means for plicating the same; means for slitting the same longitudinally; means for severing the same transversely; and means, for folding the stapled product in, on, or near, its stapled line of union; also means for supplying wire; means for cutting off successive 95 staple lengths thereof; means for carrying the staple lengths of wire to the forming device for conversion into staples; and, means for conveying formed staples to the setting devices, whether such staples are made in the 100 apparatus or delivered thereto as ready made staples.

The foregoing statements comprehend the principal or more prominent features of this invention, but, other improvements, constructions, combinations of parts and mechanisms and modifications thereof are also included within the scope of this invention, are particularly hereinafter pointed out in the claims, and explained in the course of the following 105 detailed description of the modes in which the invention is or may be practically embodied or carried into effect, a ready understanding of which description and claims will be aided by reference to the accompany- 110 drawings.

In these drawings, section lines mark the plane in which an illustration is made, the reference number for the line indicates the figure which embodies the view, and the arrow head connected with each section line points the direction in which the picture is 115 seen. Feathered arrows show the direction of movement of the parts with which each is associated, and like reference characters designate corresponding parts.

The views in Figures 1, 2, 3, 26, 27, 28 and 29, are made up on a scale about one quarter of that of the other views, but some of the views of details are upon enlarged scales to 120 more clearly show the parts and their operation.

Fig. 1, is a side elevation of duplex printing mechanisms, the delivery apparatus whereof,

is supplied with a stapling mechanism for binding the plicated products thereof, the side framing being removed from the main machine to more clearly show the mechanisms. Fig. 2, is a plan view of the same. Fig. 3, is an end elevation of the delivery apparatus. Fig. 4, is an end elevation of the delivery apparatus, removed from the machine and devoid of framework. Fig. 5, is a plan view of the same with the framework in place. Fig. 6, is an enlarged side elevation. Fig. 7, is a plan view of the staple leg clinching mechanism. Fig. 8, is a longitudinal sectional elevation thereof. Fig. 9, is an end elevation thereof. Fig. 10, is a cross sectional elevation showing some mechanisms carried by the cylinder or support C and others that co-act therewith; Fig. 11, a vertical elevation on the section line 11 of Fig. 10. Fig. 12, is a bottom face view of the parts shown in Fig. 10. Fig. 13, is a cross sectional elevation with the parts in another position. Fig. 14, is a vertical elevation on the section line 14 of Fig. 13. Fig. 15, is a face view of that part of the cylinder or support B through which a part of the stapling mechanism protrudes. Fig. 16, is a horizontal sectional plan view on the section line 16 of Fig. 17. Fig. 17, is a vertical sectional elevation on the section line 17 of Fig. 15. Figs. 18, 19, 20, 21, 22 and 23, are sectional details of the stapling mechanism in various positions of its operation. Fig. 24, is a horizontal sectional elevation of the staple clinching mechanism taken on the section line 24 of Fig. 22. Fig. 25, is a similar view taken on the section line 25 of Fig. 23. Fig. 26, is a diagrammatic projection in horizontal plane of the run of the webs or material to be stapled, and one mode of making a folded and staple bound book-like product with mechanisms organized and arranged as in the preceding figures. Fig. 27, is a side elevation of the same. Fig. 28, illustrates the book-like product, partially folded on its stapled binding line. Fig. 29, is a perspective view of the stapled and folded book-like product.

Other modifications of the invention are illustrated as follows:—Figs. 30, 31, 32 and 33, are sectional views showing in detail a modified construction of the staple setting mechanism. Fig. 34, is an end elevation; Fig. 35 a side elevation, and Fig. 36 a sectional elevation, of a modification of the rotating supports or carriers of the delivery apparatus and the mechanisms they support. Fig. 37, is a face view of the clinching device. Fig. 38, is an end or face view of the staple holding and inserting devices. Fig. 39, is a sectional elevation thereof on the section line 39 of Fig. 38. Fig. 40, is a sectional view of the staple forming devices, and staple holder. Fig. 41, is an end elevation of the rotating carriers or supports for a stapling mechanism that is adapted for setting staples longitudinally or by so inserting them in the material that their legs are parallel with its run. Fig. 42, is a plan view of a portion thereof. Fig. 43, is a

perspective view of the carrying stock for the staple holding or presenting tool. Fig. 44, is a similar view of the staple holding or presenting tool detached. Fig. 45, is a similar view of the staple holding or presenting tool within its carrying stock. Fig. 46, is a similar view of the lever for actuating the staple holding or presenting tool, detached. Fig. 47, is a partial end elevation of one of the supports or carriers, a portion being in section to more particularly show the arms of the staple holder in their relation to the openings in the carrier or support in which they operate. Fig. 48, is a plan view of the same parts. Fig. 49, is a partial longitudinal sectional elevation of a part of the same support or carrier showing an edge view of the carrying stock for the staple holder, the latter being indicated by dotted lines. Fig. 50, is a plan view of a part of the same carrier or support showing more particularly the openings in its periphery provided for the movements of the staple holder. Figs. 51 and 52, are edge elevations of the staple holder and its carrying stock in two positions of their operative relation to the forming anvil and setting bed. Figs. 53 and 54, illustrate folded products the leaves or plies of which are united to form a book by means of staples inserted through them parallel with and near their binding edges. Figs. 55 to 62, illustrate a further modification of the invention wherein the staples are inserted longitudinally or so that their crowns are parallel with the run of the material receiving them. Of these views, Fig. 55 is an end elevation, of a delivery mechanism embodying this modification, the carrier or support for the staple forming, holding or presenting, and inserting instrumentalities, being disk like. Fig. 56, is a side elevation of the same, the carrier which supports the staple forming, holding and inserting devices being shown in longitudinal vertical section, while the cams for imparting motion thereto and their supporting brackets are shown in elevation. Fig. 57, is an elevation of this disk like carrier or support in which are mounted the staple forming holding and inserting devices, portions being broken away to expose inner parts. Figs. 58 and 59, are similar views of portions of said carrier or support, showing the different positions of the mechanisms during the operation of forming and presenting a staple. Fig. 60, is a plan view partly in section of said disk like carrier or support, and its co-operating devices as seen in the direction of the arrow 60 in Fig. 57. Fig. 61, is a facial elevation of said carrier or support, showing more particularly the levers for operating the stapling mechanisms as well as their actuating cams, as seen in the direction of the arrow 61 in Fig. 57. Fig. 62, is a sectional elevation on the line 62 of Fig. 60, showing more particularly the wire guideway. Figs. 63 to 78, illustrate a rotative stapling mechanism in which the wire supplying and feeding, the staple forming, holding or presenting,

and inserting mechanisms, are all supported by a single rotative carrier. Fig. 63, is an end elevation of the principal parts of a delivery apparatus, showing more particularly the 5 stapling mechanism carriers or supports, when the stapling mechanisms are approaching the staple inserting point. Fig. 64, is a side elevation of the cylinder, carrier or support B, in a position equal to a quarter turn rearward of that shown in Fig. 63, some portions being made sectional on the line 64 of Fig. 63. Fig. 65, is a plan view, showing more particularly the wire feeding plate, the shell of the carrier being removed 10 to expose it. Fig. 66, is a sectional elevation, of the staple forming, presenting and inserting mechanisms, taken on the lines 66 of Figs. 68 and 69. Fig. 67, is a similar view, the section being taken in part on the line 67 of Fig. 20 68. Fig. 68, is a bottom plan view of Fig. 66 partly in section. Fig. 69, is a face view, partly in section, of Fig. 66. Fig. 70, is a section taken on the line 70 of Fig. 66. Fig. 71, is a sectional elevation on the line 71 of Fig. 25 69. Fig. 72, is a plan view of Fig. 71. Fig. 73, shows detached perspective views of the inner or staple crown guide, and of the wire guide. Fig. 74, is a perspective view of the staple holding and inserting devices. Fig. 75, 30 is a rear view of the outer end of the operating lever for the staple inserting device. Figs. 76, 77 and 78, are sectional elevations taken respectively on the lines 76, 77 and 66 of Fig. 68. Figs. 79 to 85, illustrate a further 35 modification wherein the staple holding and inserting mechanism, carried by the rotating cylinder or support B, receives a made staple from a suitable source of supply. Fig. 79, is an elevation partly in section of a portion of 40 the cylinder, or support illustrating the relation of the stapling mechanism thereto. Fig. 80, is a similar view with the parts in a different position. Fig. 81, is a sectional detail taken on the line 81 of Fig. 79. Fig. 82 is a 45 face view of mechanisms carried by the cylinder or support B, as seen in the direction of the arrow 82 in Fig. 80 when the shell of the cylinder is removed. Fig. 83 is a side elevation, and Fig. 84, is a perspective view 50 of the staple receiving, holding or presenting, and inserting or setting devices. Fig. 85, is a perspective view of the guards connected with the staple feeding wheel. Figs. 86 to 93 inclusive, illustrate a further modification of this invention, in which the staple holding or presenting and inserting mechanisms, have the rotative movement of oscillation. Figs. 86 and 87, are opposite side elevations showing the stapling mechanism. 55 Fig. 88, is a partial plan and sectional view, showing more particularly the wire feeding and cutting mechanisms. Fig. 89, is a longitudinal sectional elevation through the upper or staple forming member of the stapling 60 mechanism. Fig. 90, is a similar view, but shows in plan, the lower members of the stapling mechanism, viz: the staple holder or pre-

senting tool and the staple driver it carries. Fig. 91, is a front end elevation of the staple inserting tool or driver, the arms of the staple holder, which guide it, being in section. Fig. 92, is a side elevation of the wire cutter. Fig. 93, is a perspective view of the trigger cam. Figs. 94 and 95, are front and side elevations of the staple leg clinching die or block. 75

Of the many practical embodiments that may be made of this invention, those shown herein illustrate the improvements as applied to a web printing machine, and before explaining more particularly the construction 80 and the operation of the staple binding delivery apparatus, a printing machine adapted to produce and plicate printed paper webs or sheets ready for the binding operation will be described. 85

The example of the web printing machine shown, comprises printing mechanisms that are adapted to print upon paper led from the roll, two rolls being used. Each of the printing mechanisms has its forms disposed four plates abreast and four plates around its printing or type cylinders. For convenience of description the roll marked M will be considered as the main web, and the roll marked S will be considered as the supplemental web, 95 but it is to be remarked that webs of varying widths may be employed.

The web printing mechanisms shown are in general construction of a preferable form, and as that construction is well-known in the art they will be readily understood by a description of the course of the webs through them. The main web from the roll M is led over guiding rollers 131, 132 and passes thence between the impression cylinder O and type 100 or form cylinder D, whereby it is printed upon one side. From the impression cylinder O it is led between an impression cylinder E and a type or form cylinder F, whereby it is perfected by being printed upon its opposite 105 side. The supplement web from the roll S is led over guiding rollers 135, 136 and passes thence between an impression cylinder G and type or form cylinder H whereby it is printed upon one side. From the impression cylinder 110 G, it is led between the impression cylinder I and a type or form cylinder K whereby it is perfected by being printed upon its opposite 115 side.

Although the printing mechanisms are illustrated herein as having their printing cylinders each provided with four forms abreast and four forms around them, and each form is adapted to print the matter for a page, thus 120 capacitating them to print a web four pages wide, it will be understood by a consideration of the printed webs shown in Fig. 26 that the forms are for convenience, duplicated in pairs around the printing cylinders; and the two sets of printing mechanisms are shown as of 125 like capacity in order to more fully illustrate the multiplex variety of folded and bound book-like products that may be obtained 130 therefrom; but the supplemental printing

mechanism may bear the relation to the main printing mechanism in the proportion as one is to two, or to three or to four, or as two is to three or to five; or as three is to five, &c.

5 Although the delivery mechanism is shown as constituted in part by one longitudinal folder L, it might embody two, or more, as is common in the art, although one is sufficient to well illustrate the present improvements.

10 For a general description we will consider each web to be of double width, the two thus being equal to the full capacity of the printing mechanisms. In this case the main web from the roll M after being perfected will be

15 divided longitudinally into two webs by means of a slitter as 139 that co-acts with the roller 133, whereupon one of the narrow webs (the nearer) will be passed over roller 107 and be led directly onward over roller 134, to the 20 longitudinal folder; while the other narrow web will run out from the roller 133 and be turned up over the turning bar W, and then up over the turning bar U, thus being shifted or transferred laterally, under the nearer nar-

25 row web, the two narrow webs being thus superimposed so that they move onward together, as one web, over the roller 134 and onto the longitudinal folder L. The supplement web from the roll S after being perfected will

30 be divided longitudinally into two narrow webs by means of a slitter 140, that may be swung into coercive relation to a guide roller 137, whereupon one of these narrow webs, (the nearer) will pass from the roller 137 di-

35 rectly to the roller 134 and thence directly onto the longitudinal folder L, and the other narrow web will pass upward from the roller 137 to and over the roller 138 and be turned down over the turning bar V, and down over

40 the turning bar T, thus being shifted or transferred laterally over the nearer narrow supplement web, the two narrow supplement webs and the two narrow main webs thus being superimposed so that they move onward

45 together as one web, the result being that as the roller 134 is passed there will be four superimposed two page wide or narrow webs entering simultaneously onto the longitudinal folder L. The roller 134 is also sur-

50 mounted by a slitter 141 by which the webs passing over said roller may be slit in their longitudinal centers as they pass onto the longitudinal folder L, the result of which will be two side by side streams of superimposed or

55 plicated webs, each consisting of four plies. The slitters 139, 140, 141 are mounted in swinging arms so as to be moved at will into and out of operative position. This plication of the webs may be accomplished in other

60 ways, as for instance, by means of triangular transmitters, although in the production of some forms of the product the plication of the webs may be accomplished by simply leading narrow webs two pages wide or less, 65 from one or both of the printing mechanisms directly to the longitudinal folder, without using turning bars or other transferring de-

vice. Thus webs or sheets from a multiplicity of printing mechanisms arranged one above another, or otherwise, so that their webs may be led directly to the delivery mechanisms would accomplish plication, as would any means for associating the products of printing machines of many varieties. Thus the main and supplemental printing machines 75 might be arranged at right angles with respect to each other and supply printed webs or sheets to means for associating or plicating them.

The longitudinal folder L as herein shown 80 is constructed in conformity with Patent No. 331,280, but may be of any other construction adapted to perform the function of longitudinally folding or plicating material in the web or sheet form. As illustrated it consists of angularly arranged internal turning bars 101, 102, which in connection with external turners or rollers 103, 104, and fold laying rollers 105, 106, constitute a longitudinal folder upon which the paper webs enter directly from the printing mechanisms and by which they may be plicated by being longitudinally folded, or if split centrally by the slitter 141 into two side by side sets of webs, they will be plicated by the turning orlapping action of the said longitudinal folder. The associated or plicated webs thence pass onward to be cut transversely into sheet lengths, folded transversely and bound together in, on or near the line of such fold by 100 the stapling mechanisms.

The transverse cutting of the webs into sheet lengths may be performed at any convenient point of the machine which is reached by the webs after they are printed. Formerly such cutting operation was commonly performed immediately after the printing operations were complete, but this necessitated the use of carrying tapes for the conduction of the sheets onward and required the tapes to compass the mechanisms intervening the transverse cutting devices and such of the final delivery devices as was capacitated to hold each individual sheet. Such an arrangement may be used with this invention, but it is 115 preferred that the paper shall remain in the web until that part of the delivery mechanism is reached which holds each sheet length, as is herein illustrated, thus dispensing with carrying tapes, which arrangement of the cutting devices and integrity of the web has long been the substitutive equivalent of first cutting into sheets and then carrying the same 120 onward in a taped pathway.

To aid a ready understanding of the various improvements included herein, the general construction of the delivery apparatus illustrated in Figs. 1 to 29 will first be explained. It mainly consists of rotary sheet cutting and folding mechanisms that are supported by rotating carriers or supports A, B which are preferably constructed in the form of cylinders. The carrier A is, for convenience, of a size to provide a circumferential

extent equal to that of the length of two sheets to be operated upon, and it therefore is provided at opposite points with folding blades rotative in this carrier, and here shown 5 as double membered, as the blades 48, 49 and 51, 52, which folding blades co-operate in performing the folding operation with folding rollers 53, 54, as is common in this art. The carrier B which for convenience is one- 10 half the size of carrier A, or equal circumferentially to the length of one sheet, is provided with a cutting blade 20 of ordinary construction which co-operates in performing the transverse severing operation with cutting 15 slots 21, 22, with which the carrier A is provided at equidistant points midway between the folding blades. Additionally, the carrier A is provided directly in the rear of the cutting slots 21, 22 with sets of sheet impaling, 20 carrying pins 23, 24, which are respectively pivoted to rock arms 25, 26 that project from shafts 27, 28. These arms 25, 26 are rocked against the pressure of retaining springs 29, 30 by means of rock arms 31, 32, that are actuated at proper times by means of a stationary cam 33 which is so positioned with respect to the folding rollers 53, 54 that the said pins are normally projected so as to impale the paper before it is severed, and thus hold 25 the leading end of the sheet and carry it forward until it is to be folded, and then withdraw in proper time to admit the leading portion of the sheet to be drawn rearward as it is folded upon the predetermined line of 30 fold through the rotative protrusion of one of the folding blades beyond the periphery of the carrier A and into the nip of the folding rollers 53, 54. These rotary folding blades 48, 49 and 51, 52 are constructed and operate 35 substantially as is illustrated in the Patent No. 453,407, and though selected here as illustrative of the folding operation, may have substituted for them any other construction of folder, as is apparent. 40 The carriers A, B are geared together so as 45 to run in unison by means of wheels 108, 109, and the rollers 53, 54, 105, 106 will be so geared together, as to run with a like surface speed. It will be obvious that the longitudinally 50 folded paper web or associated webs, or sheets, from the rollers 105, 106 will be directed between the carriers A, B and be impaled by a set of the pins as 23, or 24, as the same pass the point of nearest contact between the 55 carriers A, B, while at the same time the cutting blade 20, co-operating with one of the cutting slots 21, 22, will sever such paper web or webs transversely, thus detaching a forward portion equal to a sheet's length. The 60 end of the web or webs from which a forward portion has thus been detached, now held by the pins 23, 24, will be laid upon the surface of the carrier A, as the latter revolves, and thus held the paper will be carried onward 65 until the central portion of a sheet's length of the web or webs is appropriately near to the folding rollers 53, 54, when the pins will

be withdrawn to release their hold upon the paper and the latter will be doubled or folded by one of the folding blades into the nip of the folding rollers; and when the appropriate length of the web or webs has thus passed onward, the cutting blade 20 will sever the same transversely and detach a sheet's length therefrom. This is an ordinary cutting, folding, delivery operation as performed in machinery of this class and is introduced here to illustrate the co-operative relation with such mechanisms of the invention constituted by the present improvements. 70 75 80

The mode of performing the binding of the plicated webs or sheets and means therefor will now be explained. As has been stated, the plicated product is to be provided with means for uniting its plies of paper thus doubled or folded together in, on, or near, its binding line. Herein the union of these plies of paper at such binding line is effected by means of wire staples, one of which is shown as applied to the folded sheet, as is seen in the sheet shown issuing from the folding rollers in Fig. 4. The mechanisms are shown as supported by cylinders C, B, A, all of which, in so far as the stapling mechanisms are concerned, are mere carriers or supports for the same, said cylinders being geared together to run in unison, so that the various devices may perfectly co-operate, the carrier or support C being preferably two or more short cylinders mounted upon a common shaft that is geared by means of a toothed wheel 110 with a wheel 109 on the shaft of the carrier or support B. In the example shown, Figs. 1 to 33 inclusive, there are three sets of rotative stapling mechanisms, arranged in longitudinal series, by which three staples are formed and inserted in, on, or near, the binding or fold line of each sheet or product. For some products two or even one staple will suffice, while for others three and even a larger number may be necessary, and hence the stapling mechanisms may be duplicated accordingly and preferably be made adjustable with respect to each other.

In order to readily understand the construction and operation of the stapling mechanisms one set will now be described, it being understood that this description of one set applies to all in the embodiment of the invention now being described. Wire of suitable size, according to the thickness of the plies to be bound together, is wound upon a spool 35 mounted to turn freely in bearings projecting from standards that are supported by a cross bar 36 secured to the frame of the machine, in which standards are suitable pairs of feeding rollers 6, 8, which are geared together by pinions 37, 38 and driven by means of a pinion 39, on the shaft of roller 8, that is engaged by the pinion 40 on the former shaft which carries a worm wheel 41 that engages with a worm 42 on the shaft of the carrier C. This constitutes the wire feeding mechanism and its feeding action is so timed as to pro-

trude a staple length of wire in front of the carrier or support C at each revolution thereof. This staple length of wire is, in the course of the operations of the mechanisms, protruded to an appropriate length in front of the periphery of the carrier or support C at such time that it will be in place in advance of the arrival of the cutting edge of one arm as 44, of the hooked conveyer, which is fixed 5 to the carrier or support C, at the wire feeding point. This cutting edge forms part of, is constituted by, or may be attached to one arm, as 44, of the pair of arms 44, 45, which, in this instance form the hooked conveyer referred to, which arms are secured at opposite sides of the face of the periphery of the narrow rim of the carrier or support C and the cutting arm is located so that it travels past the die 1 in shearing contact therewith; and 10 from this wire cutting point there extends nearly to the staple forming points, a guard 43, that is wide enough to fill the central space between the hooked conveyer arms 44, 45, is curved to coincide with the periphery of the carrier C, and preferably continues 15 into the wire protruding plane. It is supported by a shaft secured to the framework and is more or less spring-like as is required, but although it is preferably present, 20 it may be omitted. The hooked conveyer arms 44, 45 (see Figs. 3, 4, 5, 6 to 10, 18 and 19) are shaped to receive the wire in their necks and carry it onward while supported upon the face of the periphery of the carrier 25 or support C, aided by the guard 43, first forcing the same against the cutting face of the die 1 to sever from it a length suitable for the size of the staple it is to form, then carrying such wire length onward in a circular path, to the point where the staple forming devices are to act upon it. The carrier B supports a swinging forming anvil 46 upon or over which the wire length is bent into 30 staple form as said anvil descends through or between the hooked conveyer arms 44, 45, which then act as staple bending arms. This swinging anvil 46 is mounted upon a shaft journaled in the carrier or support B and is provided with a rock arm 2 through which it 35 is appropriately rocked by a stationary cam 302. The movements imparted to this swinging anvil are such that as the hooked conveyer arms 44, 45 are approaching the point where the carriers or supports B, C run nearest together, said anvil moving through a recess 40 in the periphery of the carrier C, has the nib 3 at its end brought into contact and engagement with said wire length, as in Fig. 18, so as to momentarily embrace the same between 45 it and the hooked conveyer arms 44, 45. The progressive swinging movement of the anvil 46, which is of a width to fit between the hooked conveyer arms 44, 45 with a clearance space on opposite sides equal to the thickness of the staple wire (see Figs. 12 and 16), forces the wire between said conveyer arms 44, 45, and thus not only converts it into sta- 50 ple form about the anvil, with its legs between the anvil sides and the inner faces of said hooked conveyer arms, (Fig. 14) but 70 clears it from said conveyer and transfers it within the periphery of the carrier or support B, where its legs, embracing the anvil 46, are confined within a recess in said carrier formed by face plates 74, 75. The legs of the 75 moving staple are thus supported on both sides, as in Figs. 14, 15, and the staple momentarily rests on a holder or presenting tool that in this instance has the form of a rocking forked guide 47, whose arms also embrace the anvil 46 and rest in the recesses between the sides of the anvil and the face plates 74, 75. This holder, presenting tool or forked guide 47, has forwardly inclined bearing guiding faces, and it is suitably rocked 80 by means of a cam 55 into two positions, one (see Figs. 18, 19) when the anvil is moving into the carrier or support B, and another, which is shown in Fig. 21, to properly guide or direct the staple in the presenting operation as the carrier or support B rotatively moves and is approaching the position for inserting the staple. This forked guide 47 in moving into this last position, operates to strip the staple from the anvil 46 and carry it to 85 and present it in the plane of insertion, where the legs of said staple stand astride a spring seated swinging guide block 10 that in part supports and sustains the staple during the movement of its insertion; and this swinging 90 block 10 has a guiding face for the head or crown of the staple, that is, slightly curved or recessed to allow the unobstructed upward movement of the staple as it is raised by the forked guide 47, and which block 10 acts 95 thereafter during its swinging movement from the position of Fig. 21, as a constant internal support for the staple until the staple leaves it just prior to its reaching the position of Fig. 23, which swinging movement of the block 10 is accomplished against the force 100 of a coiled spring 81 by the forward movement of the staple driver or inserting tool 56, supported by the carrier B, which driver moves in a right line guided by its side rails 105 62, 63, which move in sliding contact with guiding ledges 64, 65, near the top of the recess in carrier B in which the anvil 46 swings. This driver 56 is reciprocated by means of a toothed rack and segment, the segment 9 of 110 which is rocked for this purpose by means of a rock arm that is driven by a cam 57. 115 The clinching mechanisms, which are duplicated at each staple setting point, consist of pairs of reciprocating jaws 11, 12, which 120 move to and from each other as follows, see Figs. 4, 5, 7, 8, 24, 25: The member 11 of each set projects from a bar 58 and the other member 12 of each set projects from a bar 59, and the members 11 of one set overhang 125 the bar 59 so as to present them in the same plane with the members 12 of the other set. These bars slide upon each other in opposite directions in guideways cut in the face of the 130

carrier or support A and are slotted to receive guiding screws 60 that pass through elongated slots in the bars. These bars project at one end beyond the cylinder head and 5 are bifurcated to straddle a shaft which carries at one end a pinion 13 and at the other a rock arm 61. On opposite sides of these bars are provided short racks 14, 16, which respectively engage pinions 15, 17 that are mounted on companion shafts turning in fixed supports and which respectively mesh with said rack bars and with the pinion 13. This pinion 13 is on a shaft that is rocked by means of a rock arm 61 whose stud runs in the face 15 cam 115, the slot of which is so shaped that it will cause timely oscillations of the pinion 13 and thus reciprocate the jaws 11, 12 to and from each other at proper times, thus spreading them, as in Fig. 24, to admit the entrance 20 between them of the staple legs, and drawing them together, as in Fig. 25, to bend inwardly the two legs of the staple, that protrude through the paper and stand between them, and press down and clinch said legs upon the 25 paper.

The operation is as follows: It will now be understood that while the plicated webs or sheets Z, which are to be united by the staples and then folded in, on or near, the line 30 of stapling, are running onward from the rollers 105, 106, to and between the rotative carriers or supports A, B to an extent equal to a sheet's length, wire from the spool 35 will have been protruded across the peripheral face of the carrier or support C to a sufficient length to form a staple, by the feeding action of the rolls 6, 8, which length of wire will have been lodged in the hooked conveyer arms 44, 45, and cut off by the action of the 35 shearing side of the conveyer arm 44 and the die plate 1, and this staple length of wire thus detached and held in the embrace of said hooked conveyer, will have been conveyed around with the carrier, cylinder or support 40 C, while supported between its surface and the guard 43, and brought into the position shown in Fig. 8; and that during the same period of time the swinging forming anvil 46, then moving toward the carrier or support B, 45 will have been swung outward and entered within the recess 80 in the cylinder C so that its nib and swinging guide block will be above said staple length of wire supported in the hooked conveyer, as in Figs. 10, 18. Said 50 swinging anvil will then begin its reverse movement or swing inward, and in so doing it will, as it moves through or between said arms of the hooked conveyer, press the central portion of the wire, then lying beneath its under 55 face, as in Fig. 18, between the hooked conveyer arms 44, 45, and the recessed sides of the anvil, as in Figs. 13, 14, thus bending the end portions at right angles to the body of the wire, thereby forming a staple, the legs 60 of which staple then supported throughout their length by the sides of the anvil and the inner faces of the hooked conveyer arms, will

have such support continued, as the further swinging movement of the anvil brings it into its normal position coincident with the 70 periphery of the carrier or support B (Figs. 15, 17) and carries the staple legs between the face plates 74, 75 of, and into, the recess in the cylinder or support B, as in Figs. 16, 19. In thus swinging into the recess in the 75 cylinder or support B, the anvil moves into the embrace of the opposite arms of the forked guide 47 which then rest between the slightly recessed sides of the anvil and the face plates 74, 75 with their adjacent faces near the 80 staple legs. (See Fig. 15.) As the setting point for the staples, or that where the carriers, cylinders or supports, B, and C, run nearest in contact, is being approached, the forked guide 47 is being moved toward the guiding 85 ledges 64, 65 and finally rests in a plane that is a staple's thickness below the ledges 64, 65, which ledges, in conjunction with the arms of said forked guide 47, form channels in which the staple legs are guided, and in which the 90 staple driver 56 reciprocates. As the forked guide 47 thus moves, it strips the staple from off the anvil 46, moves it bodily upward and forces it onto the swinging or tumbling guide block 10, as in Fig. 20, where it rests in alignment with the driver 56, its head then bearing against the rear face of the guide block 10, and being in front of the driver 56, while its legs, then embracing the sides of said guide block, are supported laterally between said block and the face plates 74, 75 and vertically between 100 the arms of the forked guide 47 and the guiding ledges 64, 65, of the recess in the carrier or cylinder B. Thus encompassed by holding surfaces, this staple is held and presented in 105 position to be inserted by the driver, and it will be moved outward for insertion by the movement of the driver 56, see Fig. 21, the quick forward movement of which will force the staple outward and project its legs through 110 the paper or material opposed to them and protrude said legs into the carrier, cylinder or support A, as in Fig. 22, during which inserting movement of it the driver will also press forward and swing over or rock the 115 guide block 10 so that its sides and rear faces will continue to afford an internal support for the staple progressively decreasing during 120 and until the protrusion of the legs of the staple into the carrier or cylinder A is about complete, said block leaving the staple an instant before the head of the staple rests against the paper, sheets or material through 125 which it has been protruded. As the rotating carriers, cylinders or supports A, B, are rotatively moving the staple holding or presenting, the inserting, and the clinching devices or mechanisms onward and these devices are approaching the setting point for the staple, which is where these two carriers or cylinders 130 run nearest together, the jaws 11, 12, of the clinching mechanism will have been opened, as in Figs. 22, 24, and when the protrusion of the staple legs is complete, as in Figs. 23, 25,

the jaws 11, 12, will quickly move toward each other or close, and, engaging said staple legs, will bend them toward each other and clinch them down upon the surface of the paper or 5 sheets in opposition to the head of the staple which rests upon the opposite surface of said paper or sheets, as in Figs. 23 and 25. The stapling of the paper, sheets or material in, on, or along, the binding or line of ultimate fold, 10 being finished while the same is being carried onward to the folding devices, the wire feeding, staple forming, holding or presenting, driving or inserting, and, clinching devices, begin their reverse movements and complete 15 the same in time to perform or repeat their operations just described in stapling the succeeding sheet length of material. This binding line or that of ultimate folding of the material overlies that part of the carrier A where 20 a folding blade, as 52, is positioned, and a portion of the edge of such folding blade is therefore removed to accommodate both the protrusion of the staple legs within the peripheral surface of the carrier or cylinder A, 25 and also provide for the presence and operation of the clinching devices. The plicated sheets, or sheet lengths of plicated webs, stapled together on their transverse binding line, are carried onward in the usual manner 30 until said stapled binding line or that of ultimate folding is, by the rotative movement of the carrier or cylinder A, brought over the folding rollers 53, 54, whereupon said folding blade, as 52, will be moved outward to double 35 the plies of paper or sheets on the stapled line of their union through said folding rollers, the impaling pins as 23, holding their leading ends, simultaneously releasing the paper or sheets. The product thus doubled 40 or folded transversely upon its stapled or binding line of union of the plies composing it, as in Fig. 4, will be delivered from these rollers 53, 54, and the folded and bound pack may pass outward therefrom for final delivery, as between tapes 70, 71, the former running from a roller beneath the folding roller 54 and the latter running from a companion roller beneath the companion folding roller 53, which tapes, as here shown, run oversuit- 45 50 able pulleys or rollers and form a pathway carrying the plicated staple bound packs to an S-fly 50, whereby they are deposited upon delivery tapes 315, but they may be delivered in any common manner.

55 Before entering upon a description of the various modifications which may be made in the practical embodiment of this invention, a general description will be given of the making of some of the bound book-like products, 60 which the mechanisms thus far described will produce. With this object in view, we will assume, as is indicated by the printed webs shown in Fig. 26, that the main printing mechanism has its type or form cylinders each provided with eight printing plates or forms, four abreast and two around it, (taking no note of their duplication around the cylinder) which plates are appropriate for the production of the main web for a twenty page pamphlet or book-like product, each set of 70 sheets cut from which main web will constitute the sixteen inside pages of the ultimate product, and that the supplement printing mechanism has its type or form cylinders each provided with two printing plates or forms 75 around it, (taking no note of their duplication around the cylinder) which plates are appropriate for the printing of four pages of such twenty page product, each sheet cut from which supplement web will constitute 80 the outside pages or cover of the ultimate product; and for the purpose of better distinguishing the supplement web and the cover made from it, we will assume that it is printed upon green paper (indicated in Figs. 26, 27 85 and 29 by shading) while the main web is printed upon white paper. In this case the white main web from the roll M will be four pages wide and the green supplement web from the roll S will be one page wide. The 90 main or white web M will be printed on one side in passing the printing cylinders O, D, and be printed upon the other side in passing the printing cylinders E, F. This perfected white main web will be divided in its longitudinal center in passing over the roller 133 and under the slitter 139, and thus be divided 95 into two narrow or two page wide webs. One of these narrow webs, the nearer, will be led over roller 107 and pass thence over roller 134 100 onto the longitudinal folder L, while the other narrow web passes from the roller 133 to and is turned up at an angle of forty-five degrees over the turning bar W and again turned up at a like angle over the turning bar U and 105 then runs onward on top of its companion narrow web and with it enters upon the longitudinal folder L. The single page wide green supplement web S is printed on one side in passing between the printing cylinders 110 G, H and then on the opposite side in passing between the printing cylinders I, K, but it might be printed upon one side only and upon the area of one page only if so desired. This perfected web runs over roller 137 and 115 passes between the turning bars T, U and joining the two narrow main webs it lays on the top of them over the nearer half of the narrow main webs and these associated webs run over the roller 134 onto the longitudinal 120 folder. In passing this roller 134 the two associated narrow or two page wide main webs are divided longitudinally by the operation of the slitter 141 and the side by side streams of narrow or one page wide webs, one, (the 125 right hand stream as the longitudinal folder is viewed from the front) consisting of three webs and the other consisting of two webs, are combined or plicated by the lapping operation of the longitudinal folder. As these 130 one page wide webs emerge from between the laying rollers 105, 106, their plies are five in number, four upon white paper from the main web roll, and one, upon green paper

from the supplement web roll, and as these plicated webs pass between the carriers A, B, the supplement or cover web is upon the side facing the carrier B. This plicated pack 5 (represented for convenience of illustration in Figs. 4, 20, 21, 22, 23, 30, 31 and 32, as composed of but two plies) will have its leading ends impaled by the pins 23 or 24, and thus be laid upon the surface of the carrier A and 10 be carried around with it in its circular path, and when the plicated pack of five plies has suitably passed between the carriers A, B, so as to properly present its binding or folding line thereto, the stapling devices will insert 15 staples through the pack from the cover side and clinch the same upon the opposite side, as is indicated in Figs. 27, 28, 29. When a length of the plicated pack equal to the length of an unfolded sheet passes between 20 said carriers A, B, the cutting blade 20 will, co-operating with the cutting slot 21 or 22, cut the plies transversely and thus detach from the webs the component parts of the twenty page product, which will, when properly presented, in its circular travel to the 25 folding blade as 48, 49 or 51, 52, and the folding rollers, 53, 54, be doubled or folded upon its stapled line of union and be delivered folded, as is shown in Figs. 4, 20, 29, with the 30 heads or crowns of the staples on the outside of said binding line and the legs of said staples clinched within the bight of said folding.

While a printing machine capacitated to carry out the operation just described comprehends a practical demonstration of the great utility of this invention, although it requires a supplement printing machine adapted to print but a single or one page wide web, it will be observed that when the supplement machine is equal to the printing of a four page wide web, a great variety of staple bound folded products may be obtained. Some of these are:—Either printing machine provided with plates therefor and printing a double or two page wide web, would make a folded stapled product of four leaves or eight pages, and the same product would be made if each machine printed a single wide web. The main printing machine printing a two page wide web and the supplemental printing machine printing a single wide web, would make a folded stapled product of six leaves or twelve pages. Either machine printing a four page wide web would make a folded stapled product of eight leaves or sixteen pages. The main machine printing a four page wide web and the supplement machine a two page wide web, would make a folded stapled product of twelve leaves or twenty-four pages. The main machine printing a four page wide web and the supplement machine a three page wide web, would make a folded product of fourteen leaves or twenty-eight pages. Both machines printing four page wide webs, would make a product of sixteen leaves or a thirty-two page product.

Staple forming, holding or presenting, in-

serting and clinching mechanisms, having the general characteristic construction of those heretofore described may be modified greatly. 7c Of the modifications, those shown in Figs. 30 to 33, will now be described. In such construction the spring-seated swinging guide block 10 is a long lever like arm pivoted to the cylinder B instead of to the swinging anvil, and consequently is forced upward as the staple is driven outward, but like the device for which it is a substitute, it constitutes an internal support for the staple constantly decreasing in extent as the said staple is advanced or protruded from the carrier or support B until the staple finally passes off from its end as the staple is forced home or completely set in place with its head against one side of the paper or sheets through which it has been 85 passed. Thus it is normally pressed against the end of the swinging anvil ready to receive the staple as in Fig. 30, and remains in that position while the staple is carried onto it and brought into its horizontal or presenting plane, 90 by the action of the forked guide 47, as the latter is swung upward, see Fig. 31, and this block 10 is progressively raised as the driver 62 moves forward until it finally moves out of or from behind the head of the staples as 95 the latter is inserted in and forced home upon the surface of the paper, as in Fig. 32.

Other modifications are embodied in Figs. 34 to 40 inclusive. In this embodiment of the invention the rotating carrier C is omitted, 100 and the carriers or supports A, B, which support all of the staple carrying or presenting, driving or inserting, and, clinching, mechanisms, tools or devices, are made of equal size and each carries a duplication of mechanisms, and, the wire from which the staples are to be formed is delivered within the range of action of the mechanisms supported in carrier B, from a wire feeding mechanism attached to the framing. The carrier or support A supports two cutting blades 90, 91 that co-operates with two cutting slots 92, 93 provided in the carrier or support B. The pins 23, 24 for holding the leading ends of the plicated webs and sheets are the same in their construction and operation as those hereinbefore described, as are the rotative folding blades 48, 49 and 51, 52 and their co-operating folding rollers 53, 54. The staple leg clinching device, however, is modified and consists simply of properly shaped grooves 66, 67, that preferably are inclined on all sides to adapt them to receive and their ends near their bottoms are slightly curved to facilitate them to appropriately turn or bend 115 the staple legs toward each other or down onto the plicated webs or sheets. As here shown these clinching grooves 66, 67 are formed in metal blocks that are attached to the carrier A by means of screws, as is shown 120 in Fig. 37.

There is a wire feeding mechanism for each set of stapling mechanisms, considered in their longitudinal arrangement in the car-

rier. Each consists of a pair of feeding rollers 68, 69 between which the wire passes and is frictionally driven forward from a reel or spool 72, and protruded through a tubular 5 guide block 77 and within the range of rotative travel of the stapling mechanisms supported by the carrier B. The larger roller 68, against which bears the roller 69, is fast upon and is driven by means of a worm wheel 73, that is rotated by a worm 76. The worms 76 are fast upon a shaft 114 that is so geared with the carrier B that the feeding action of the rollers 68, 69 during each half revolution of the carrier B, is such as to deliver a staple 10 length of wire through the guide block 77 and protrude the same across the pathway in which the stapling mechanisms of the carrier B rotatively travel, and beneath the forming anvil 82, as in Fig. 35. The forward edge 4 of one arm 78, of the two armed traveling staple holder or presenting tool, acts as a shearing cutter in passing the end of the slotted wire guide 77 and severs a staple length of wire, which is thus detached while within the 15 range of action of the forming anvil 82, which is curved over the top of the carrier B where it hangs fixedly pendent from the framework. (See Fig. 34.) This anvil 82 (see Fig. 40) has a width equal to the inside length of the crown 20 of the staple to be formed, a thickness preferably at least equal to the length of the staple legs, and an under or face surface, the forward or main portion of which is coincident with the periphery of the carrier B, (see Fig. 25 36,) and it is sustained in proper relation to the moving devices of the stapling mechanisms, by means of shafts or rods that are secured to the framework, upon which it is made adjustable by means of set screws. It is additionally preferably shaped at its rear end 30 so as to form wings or sidewise projections 18, 34, to guide the incoming wire and act as a support for the entire wire length delivered beneath it, which support is continued a short 35 distance forward from its rear end, and this rear end is shaped to form a wedge like pathway or entrance beneath it for the rotatively moving staple holder or presenting tool during the formation of the wire into a staple. 40 The forward end of this anvil 82, where the staple progressively leaves it, is cut away so as to provide for the passage of the plicated material between the carriers A, B. Thus cut away this forward end of the anvil forms 45 a wedge or continuously decreasing guide for the staple during its progressive insertion through the material and its setting and clinching, and preferably this wedge like guide will be continued downward so far that 50 the traveling staple will leave its end just at the moment the clinching of said staple is completed.

The staple holder or presenting tool and the driver or inserting tool 85 are contained 55 in carrying stocks as N, which are fast on the shaft of the carrier B and thus are moved therewith and rotatively carry the said sta-

pling tools to and from the setting point for the staples. In this example the two arms 78, 79 of the holder or presenting tool project 70 from a hollow shank that slides to a slight extent in the carrying stock N, in which it is seated upon a spring 316 that constantly presses it outward, as will yet appear; and the inserting tool, or driver 85, not only slides 75 between the arms 78, 79 of the staple holder, but is provided with a shaft like stem 317, that plays within the hollow shank of the holder, and in a bottom guide 86, and it is seated upon a spring 320 by which it is constantly pressed outward to cause the staple to be inserted in the material, and so as to be held in position to aid in the formation of a new staple. Those parts of the arms 78, 79 of the holder and that part of the inserting tool 85 or driver 85, which are in advance of the wire bending or staple forming portion of them, are recessed or beveled so as to admit of their unobstructed movement past the protruded wire, (see Figs. 36, 38) but those parts of the 90 holder and driver that are rearward of their wire bending or staple forming line, are extended outward so as to sweep, in their rotative travel, into the plane occupied by the protruded wire, the arms 78, 79 passing close 95 to the under face of the winged rearmost portion of the forming anvil 82, (see wings 18, 34, Figs. 35 and 36,) and the inserting tool or driver all passing close to the under face of said anvil. These parts thus come into 100 contact with a staple length of the protruded wire, which wire length while momentarily supported between the outer faces of the arms of the moving holder or presenting tool and the face of the inserting tool or driver, 105 and the under faces of the wings 18, 34 of the anvil, will be severed by the action of the cutting edge 4, in passing the wire slot in the block 77. This detached staple length of wire will thus be carried onward in a circular pathway by the rotative travel movement of the presenting tool or holder and inserting tool, or driver. During this onward movement, the arms 78, 79 of the holder will maintain their position of outward protrusion by means of the efficient power of their supporting spring 316 and progressively overlap and travel close to the sides 83, 84 of the anvil 82, while the wedge like pathway or rear end of the curved anvil 82 will, as the 110 wire length is carried over it, operate to press inwardly the central portion of the wire length that has entered beneath it, thus forcing its central or crown portion and the driver or inserting tool beneath it upon which it 115 rests, within the vertical channels cut in the facing sides of the arms 78, 79 of the holder. As the wedge like portion of the curved anvil thus presses the wire length and driver inwardly, the central portion of said wire 120 length, which is to constitute the head or crown of the staple then held clamped between the inner face of the anvil and the outer face of the driver, will remain straight 125

130

or horizontal and be carried bodily within the arms of the holder, during which operation opposite ends of the wire length, which primarily lie over the ends of the arms 78, 79, 5 will be forced into bending guiding channels which are cut vertically in the inner faces of the arms of the holder, said ends being thus forced or bent outward or at right angles to the central crown or body portion of the wire 10 length, to convert them into staple legs. In this staple forming operation in which the arms 78, 79 act as benders, in conjunction with the anvil 82, these wire ends or staple legs will progressively descend into said channels 15 until the thickest part of the anvil 82 is reached, when the staple will be completely formed and be inclosed on all sides, as in Fig. 40. The formed staple is thus seated within the holder with its crown or head resting 20 upon the inserting tool or driver and having its legs embraced in the channels of the arms 78, 79, of the holder. In consequence of their protrusion beyond the periphery of the carrier B, said anvil will, in approaching the 25 setting point, first come into contact with the plicated material near the point where the forward end of the anvil 82 begins to assume the wedge shaped termination, but the relation of the parts is such the stock N being 30 arranged longitudinally that at this time the staple legs are presented at or directed toward the point in the material where the staple is to be inserted therein in such a plane that the insertion of the staple legs 35 will then be accomplished by their forward movement substantially at right angles to the plane of the travel of the material, and, as the material, and the stapling mechanisms, then all move concertedly onward to the actual 40 staple setting point, the ends of the arms of the holder or presenting tool will press the material toward and finally against the surface of the carrier A, and, opposed by the surface of the carrier A, or the clinching device, 45 will in turn press the arms 78, 79 inwardly against the action of their spring 316, while the material runs onward between the carriers A, B. The result of this is that the staple legs are progressively inserted through the 50 material, entered into the groove of the clinching device 67 and moved toward the carrier A until the crown or head of the staple is pressed against the material on one side and its legs are clinched against it on the other side. The clinched staple will then be carried wholly by the material in which it is set, 55 and, as the carriers A, B, move onward, the arms of the holder or presenting tool and also the inserting tool or driver, will be protruded or moved outward by the action of their 60 springs, and, during their rotative travel they will assume their first described positions and repeat the operations just described. The stapled material will be carried onward by the 65 pins 24 or 23, be severed into sheet lengths by the cutters 90, 93 or 91, 92, and the associated stapled sheets will be folded in, on or

near, their stapled line of union, substantially as set forth with respect to the first delivery apparatus described. The arms 78, 79 of the 70 holder may be nicely fitted so as to travel close to but not in wearing contact with the sides of the stationary anvil 82 and the inserting tool, or driver 85, will, although it is pressed inward by the action of said anvil, 75 be protected from frictional wear therefrom by reason of the interposition of the wire length to be acted upon, each wire length instead of the tools receiving the frictional wear incident to its conversion into a staple and 80 carriage to the setting point.

A more complete exposition of this modification will be found in my application Serial No. 477,778, filed June 16, 1893, which explicitly embraces the same. 85

As thus far described the mechanisms are adapted for setting staples whose heads or crowns lie transverse to or at right angles with the path of travel of the plicated material.

Another modification of this invention now 90 to be described is illustrated in Figs. 41 to 54 inclusive, and provides for the setting of staples with their heads or crowns in planes parallel with the path of travel of the material to be stapled. In this modification, webs or 95 sheets doubled longitudinally in passing the longitudinal folder L and thus consisting of a number of plications united by a doubled or folded edge, or, of webs or sheets which are plicated in passing over the longitudinal 100 folder, slit centrally and thus given free binding edges, or, consisting of two or more sets of plicated webs or sheets having doubled or folded binding edges, led from two or more longitudinal folders and brought together or 105 superimposed, may be united near to and parallel with their binding edge or edges by means of staples passed through them so that the heads or crowns of the staples rest upon one surface of the pack while their legs are 110 clinched down upon the opposite surface of the pack. The mechanism shown for carrying out this method of binding a plicated product with staples will now be described. In this construction the wire length cutting 115 mechanism, the staple forming, holding or presenting and driving or inserting mechanisms, are all supported by the carrier B, and the wire is fed to them, by means of suitably moved feeding rollers 116, 117, through a circumferential groove 118 that is cut into the periphery of the carrier B, and in which the wire is held by a spring bearer 119. The staple holder or presenting tool 100 (see Fig. 44) is recessed transversely so as to provide it 120 with arms 95, 96 which provide between them a suitable recess whereby the holder is adapted to embrace the forming anvil 94, and setting bed 99, (see Figs. 47, 52.) Its said arms 95, 96 are also provided with grooves that coincide with or form a continuation of the wire receiving feeding groove 118, and said arms are furthermore provided in their inner faces 125 with longitudinal grooves, (see Figs. 44, 45) 130

into which the wire is first forced to form the staple legs when these arms act as benders in conjunction with the anvil 94, which arms also act to move the staple into the setting bed, 5 and, as a carrying and presenting tool for the staple while transferring it into position for its insertion into or through the material. This holder or presenting tool 100 is supported so as to slide longitudinally in a carrying stock 120 that has at its outer ends pairs of arms 143, 144 and 145, 146, between which the arms 95, 96 of the holder or presenting tool are guided, and these arms 143, 145 and 144, 146 form a recess that enables 10 the carrying stock to pass the forming anvil 94 and setting bed 99. The arm 95, of this presenting tool 100 and the arms 143, 145 of its carrying stock 120, protrudes into a recess 97, and the arm 96 of the presenting tool and 15 the arms 144, 146 of the carrying stock 120 protrude into a recess 98, said recesses 97, 98 being cut lengthwise through the shell of the carrier B and made long enough to enable the presenting tool, and its stock, to swing therein 20 in the direction of the shaft of the carrier B. The holder or presenting tool and its stock are mounted to swing concertedly by means of studs 121, 122 by which they are journaled in socket arms 123, 124, that project from a bracket 125 that is fast upon the shaft of the carrier B, and this holder or presenting tool is rocked at suitable times and to an appropriate extent to perform its various functions by means of a rock arm 126 and a face cam 25 127 whose retaining sleeve, embracing the shaft, is fixed to the framework, and the said holder 100 has its bifurcated lower end pivoted to the rocking lever 128 that has one end pivoted, by a shaft 129, in arms of the bracket 30 125, while the free opposite arm of said lever 128 bears upon a fixed cam 130, by which the requisite movement of reciprocation of the holder 100 is accomplished, while admitting of a concerted rocking action with its carrying stock 120. Normally the stock 120 and 35 with it the holder 100, are held in the vertical position of Fig. 52 by the action of the cam 127 aided by the spring-seated rod 346, and the holder is maintained within its stock 40 by reason of its lever 128 resting upon the low part of the cam 130 held by the pressure of the spring-seated rod 147 on the heel of the lever 128. The shell of the cylinder or support B between the recesses 97, 98 is perforated to form a wire passage between the forming anvil 94 and the staple head supporting or setting bed 99, the under surface of which anvil 94, and the upper surface of which setting bed, are suitably inclined to admit the 45 traverse of the wire and staple head over them. As these mechanisms are introduced here simply as illustrative of a modification of the broad invention, it will only be necessary to add a description of their operation. The carrier B constantly rotates, as in the other embodiments of this invention. The wire from which the staple is to be formed is ap- 50 propriately fed onward, at suitable intervals, to cause a suitable length of it to be presented to each of the staple forming mechanisms 70 at the wire receiving point, said wire being constantly maintained in the guiding groove 118 by means of the spring bearer 119, and is thus directed within the groove in the arms 95, 96 of the holder 100 as the latter passes 75 beneath it, in its rotative onward travel, which holder normally stands with the grooves in its arms aligned with the wire groove 119, as in Fig. 48, it being thus held during the appropriate portion of its rotative onward travel 80 to receive the wire, by its arm 126, traversing the intermediate part *p*, of the stationary triple part cam 127. As its rock arm 126 passes onto the low part *r*, of said cam, the holder will be moved to and be held in its extreme left hand position, to co-operate with the anvil 94 in forming the staple; and when 85 said rock arm 126 passes up onto the highest part *f* of said cam 127, it will cause the holder to move to its extreme right hand position, to 90 carry the formed staple onto the setting bed. When the rotating carrier B has brought a carrying stock 120 with its staple holder 100 into the position of Figs. 47 and 49 it will have embraced a wire length, and thereupon 95 the low part of cam 127 will be entered and traversed, thus permitting the spring rod 346 to rock the carrying stock 120 and the holder 100 it contains, and this movement will be to the left and consequently the holder will swing 100 in a direction toward the forming anvil 94. The first slight movement thus performed will, as may be better understood from Fig. 48, cause the arm 96 of the holder to quickly force said wire length past the contracted 105 mouth of the groove 118 or die plate 89, and thus sever the wire length resting within the groove in the arms 95, 96 of the holder, which wire length will be held and carried thereby, aided by the arms 145, 146 of the stock 120, un- 110 derneath the anvil 94 as in Fig. 51, and while the parts are passing beneath or momentarily rest under said anvil, the cam 130 will rock the lever 128 to cause the holder 100 to move outwardly, its arms 95, 96, then operating to 115 force the outer ends of the wire length upward around the forming anvil 94, thus causing the wire length to be bent into a staple by providing it with legs bent at right angles to its body or crown portion, which legs will then be confined in the inner side grooves of the arms 95, 96 of the holder, by their own resilient action. When the staple has thus been completely 120 formed it is supported in the grooves of the holder arms and protruded considerably beyond the periphery of the carrier B. A reverse rocking movement of the stock 120 is now effected, as the rock arm 126 passes onto the highest part of the cam 127, thus moving the formed staple to the right, the staple being thereby stripped from off the forming anvil 94 and caused to slide up over the inclined upper face of the setting bed 99, which thus 125 operates as a wedge to force the staple up- 130

ward or outward in the inner side grooves of the arms 95, 96 (but still maintained therein) until the radial position of the holder, or that of Fig. 52 is reached, when the head or crown 5 of the staple will rest on its final seat upon the setting bed or substantially upon a portion of the periphery of carrier B in its setting position, at which time, if desired, the cam 130 may move the holder slightly outward to compensate for this outward movement of the holder, although advantageous, need not take place. In this position of the parts 10 the staple rests upon the periphery of the carrier as a solid setting bed and protrudes a distance therefrom equal to the length of its legs, which are confined in the grooves of the arms of the holder or presenting tool, and the staple is thus carried onward or toward 15 the carrier A into the presenting position relative to the material, when, by the continued movement of the parts the staple legs are inserted through the material. After its legs have entered through the material to be 20 bound and the arms of the holder come nearly in or into contact with the periphery of the carrier A, or the opposed clinching device, the said holder will retire by means of the suitable shape of the cam 130 concertededly 25 with the cam like action which the carrier A, or the clinching device, thus performs, the result being that the protruded legs of the staple are thus presented to and entered through 30 the material, and projected within the peripheral line of the carrier A, until the head or crown of the staple rests snugly against the inserting side of the material, its legs being progressively clinched, and the holder concertededly retiring. As soon as the clinching action 35 is complete and the holder is making its return rotative movement to receive and act upon a new wire length, the intermediate part p of the cam 127 is traversed and causes the rock arm of the carrying stock 120 to rock the holder 100 into the position of Fig. 49 in readiness to repeat the operation described. As 40 in the other constructions any form of clinching devices may be used. Herein, however, a modification of the clinching device is shown. 45 This consists of a clincher which is in the form of a pendent arm 148 that rests in a groove cut for it in the cylinder A, and at its bottom end this arm presents a rigid downwardly curved surface which the protruded staple legs engage as they are carried past it. The 50 staple legs in passing it are forced against the face of the clincher, contact with which causes said legs to be bent in succession in rearward directions and thus to be clinched down upon 55 the material. In using this construction of clincher, it is preferable to construct the leading arm 95 of the holder somewhat shorter than its fellow 96, (see Fig. 41,) for the reason that as they are connected together they must 60 move concertededly. Hence by shortening the arm 95 it will not contact with the clincher or the periphery of the cylinder A until the lead-

ing staple leg has been so far bent downward to secure its position, while its rearward leg is fully supported in the groove of the arm 96 70 acting as a retaining wall, and the rearward leg of the staple will be similarly supported while it is being bent downward or clinched. The appropriate retiring movement of the holder is provided for by a suitable shape of 75 the cam 130, but it might be spring seated so as to be pressed inward and recover its operative position by the resilient action of a spring. When the arm 148 is used it will be wide enough to afford contact bearings for the 80 arms of the bender. In this modification, the carriers or supports A, B are provided as before with cutting mechanisms for severing the sheets, but if desired, an auxiliary mechanism for severing the sheets, independent of 85 these carriers, may be provided. If the cutting mechanism is carried by these cylinders A, B, as is shown, it will be apparent, since they co-act at the point where the staple leg clinching is performed, namely where the cylinders run nearest together, that the pendent clinching arm 148 must be moved to accommodate this cutting operation. For that purpose this arm is hung on a pivot as 149 projecting from a bracket and pressed to 90 duty, as a clincher, by means of an arm 150 that rides upon the surface of the cylinder A, and is retired within a recess in that cylinder by the action of a spring 151, and a rock arm, when the rock arm enters a cam depression 308 in the cylinder A, whence it results that when the cutting blade is passing the point occupied by it, the clincher will not interfere with a proper cutting or severing of the material. (See dotted lines Fig. 41.) As 95 the stapling operation, when performed as in this modification of the invention, causes the staples to be set longitudinally or in the direction of the run of the material, the carrier B supporting the stapling mechanisms should have a circumferential extent equal to the length of a sheet, but it might be less or it might be greater. A companion carrier, as A, may also be present or absent, as is best suited to the character of the work to be 100 performed. The carriers A, B, shown are each of double size, or have a circumference equal to the length of two sheets, and hence they are provided with two transverse cutters 90, 91 that co-operate with two cutting slots, 105 as 93, to sever suitable sheet lengths. When the cylinder B is of double size it will be necessary to provide it with a suitable number of stapling mechanisms, according to the nearness of and consequent number of staples which it is desired that each sheet shall have. Thus, four stapling mechanisms are 110 shown in Fig. 41 and they are so positioned as to insert two staples in each pack of sheets, as is shown by Fig. 53, but in large sized products three, four or more will be desirable. The carrier A may be provided with double 115 folding blades, as is the carrier A, in the preceding figures, if it is desired to fold the pro-

duct across its binding edge after it is stapled, as is indicated by the double folding blade shown. But ordinarily such folding will not be desirable except when the printed product is large, and therefore the staple bound product will preferably pass from the stapling mechanism to any suitable final delivery or piling apparatus. In case the cylinder A is provided with one or more folding blades as stated, the same must, if a fixed clincher is used, be cut away to unobtrusively pass it as herein before explained. If now the printing plates or forms be disposed so that their columns run around the type or form cylinders, the plicated webs, whether split and associated either before or in passing over the longitudinal folder L or, remaining intact, are longitudinally folded thereby, but, delivered by this mechanism, they will be united by a line or row of two or more staples inserted through them parallel with and close to their binding or folded edge. This will give a large number of book-like products plicated or folded, and stapled, as will be readily apparent to those skilled in the art of printing. Thus, if one of the printing mechanisms is provided with plates therefor and prints a double or two page wide web and the other printing mechanism with plates therefor and prints a single or one page wide web, or one of said printing mechanisms is provided with plates therefor and prints a three page wide web, a folded stapled product will result consisting of three leaves or six pages. If either printing mechanism is provided with plates therefor and prints a four page wide web, or if each printing mechanism is provided with plates therefor and prints a double or two page wide web, the folded stapled product resulting therefrom will consist of four leaves or eight pages. If the main printing mechanism is provided with plates therefor and prints a four page wide web and the supplement printing mechanism prints a one page wide web, or if the main printing mechanism prints a three page wide web and the supplement printing mechanism prints a two page wide web, the folded stapled product resulting therefrom will consist of five leaves or ten pages. If the main printing mechanism is provided with plates therefor and prints a four page wide web and the supplement printing mechanism is provided with plates therefor and prints a two page wide web, the folded stapled product will consist of six leaves or twelve pages. If the main printing mechanism is provided with plates therefor and prints a four page wide web and the supplement printing mechanism is provided with plates therefor and prints a three page wide web, the folded stapled product will consist of seven leaves or fourteen pages. If the main printing and supplement printing mechanism are each provided with plates therefor and print a four page wide web, the folded stapled product resulting therefrom will consist of eight leaves or sixteen pages. All of these folded or plicated

webs or sheets, received from the longitudinal folder, will be united by a seam of stapling parallel with and near the binding edge 70 of each, as appears in Figs. 53 and 54, according to the number of stapling mechanisms with which the carrier B is provided.

A more extended description of this modification will be found in my application, Serial No. 483,191, filed August 15, 1893, which explicitly embraces the same.

In the modification shown in Figs. 55 to 62, is illustrated a substitute for the carrier or support B, which is disk like in character 80 and which carries staple forming, presenting and inserting mechanisms, adapted to set a staple parallel with the run of the material to be stapled, as will now be explained. It should first be stated that the longitudinal 85 folder 194 herein shown, though of ordinary construction, being substantially the structures shown and described in Patent No. 331,280, may be of any suitable construction. It is here shown as operating simultaneously upon 90 a multiplicity of webs, as the four marked W', E², B³, S⁴, which may be the product of as many printing or other web delivering machines. These webs will, although shown by single lines, as they pass between the external turners or rollers 195, 196, the carriers or supports A, B, fold laying rollers 197, 198 and cutting folding cylinders 199, 200, consist of twice as many plies as there are webs. There might be two or even more of these longitudinal folders, and the plicated products from each be brought together before being subjected to the stapling operation. In this modification, the carriers or supports A, B, are disk like, and thus bear on a narrow width 95 of the material near and including its folded edge, all of the plies of the material Z being pressed together in passing between the rollers 197, 198, while they are, or may be, compacted at or near their binding line by the 100 carriers or supports A, B. The cutting folding cylinders 199, 200 carry respectively a cutting knife or blade 201 and a cutting groove or slot 202, by which the web or webs will be severed transversely along lines a 115 sheet's distance apart; and although not shown it is to be understood that these cylinders may be provided with sheet carrying, cutting and folding devices, substantially as are the like cylinders or carriers in 120 some of the preceding embodiments of the invention. The cylinders 199, 200 are geared together by toothed wheels, one 204 on the shaft of cylinder 200 only being shown, and the carriers or supports A, B are likewise 125 geared together by toothed wheels, only one 205 on the shaft of carrier B being shown, and the said wheels on the cylinder 200 and carrier B are connected by an intermediate 130 206. Said parts thus run in unison and they will be geared with and driven from the main or printing machine so as to move concertedly with such of its parts, over or between which the paper web or webs or sheets pass.

The external turners 195, 196 when in roller form, as shown, and the fold laying rollers 197, 198 may, if desired, be so geared as to be driven in unison with the other web guiding or carrying devices. It will be understood that a web or webs caused to pass over the longitudinal folder 194 will be doubled or folded longitudinally, and that said fold will be pressed flat or laid smooth in passing between the carriers or supports A, B, or the fold laying rollers 197, 198; also, that suitable lengths of such folded or plicated web or webs will be severed to constitute sheet lengths by the action of the cutting devices 201, 202, and that such sheet lengths will be carried within the range of action of the rotative folding blade and be folded transversely thereby; and it will be obvious that the said rotative folding blade may be omitted, if desired, and the longitudinally folded sheets be delivered, after the cutting devices have formed them, by any suitable mechanism.

To perform the operations of forming, presenting and inserting the staples while the web or webs or sheets Z are on the run, so that said staples will lie in, near or be aligned with said binding line, the carrier or support B is provided with novel mechanisms for forming, presenting and inserting the staples, and preferably, a co-operating carrier or support is provided with a co-acting clinching device whereby the legs of the staple are clinched down upon the webs, or plicated material. This carrier or support B is disk like and is mounted fast upon the shaft 207. It is provided with a rim having cut into it, concentric with its periphery, a wire guiding groove 211 into which is fed the wire 210 from which suitable lengths are to be cut to form the staples. This wire is fed forward in this groove from a spool, by means of feeding rollers 208, 209, driven at a suitable speed, from which rollers said wire is entered through a stationary guide block 212 having a laterally bent channel 213. (See Fig. 61.) This guide block is supported by a bracket 214 and consists of two members between which are embraced a plate 215 the forward end of which has an inner edge parallel with the inner wall of the groove 211 and so curved that it enters into said groove and practically forms with said inner wall a continuation of the wire channel. (See Fig. 62.)

The web or body of the carrier or support B has a part or section removed to accommodate the swinging movement of some of the devices, which are supported by an arm 217 fixedly secured to the carrier shaft 207, and which arm carries journal bearings for the rock shaft 218 that supports the levers carrying the two arms m, n, of the staple holding and presenting tool, and the staple inserting tool or driver 219, all of which levers are capable of independent movement either with or upon that shaft as will presently appear. The rim of the support or carrier B has a section removed that will accommodate the

movements through it of the arms m, n of the holder or presenting tool, and the driver 219, and to provide for a lateral movement of the forming anvil 220, (see Figs. 58, 59,) where the side of this opening is shown. The forming anvil 220, is a block of metal having a length equal to the distance between the outsides of the two legs of the staple which is to be formed about it, a width about equal to that of the rim from its inner face to and inclusive of the wire channel therein, and a thickness equal to that of the carrier rim between its periphery and the outer wall of the wire channel 211, or as great as the length of the staple legs which are bent over it. It is securely attached at one side of a curved spring plate 221, that spans one side of the recess cut through the rim of the carrier, (see Fig. 60) which spring plate 221 is provided with elongated holes by which it is secured to one side of the rim by means of screws that pass through said holes, the anvil being thus enabled to have considerable lateral movement. Thus constructed and mounted, this anvil normally forms by its under or interior curved surface, a continuation of the outer wall of said wire channel 211, and its exterior surface forms a continuation of the periphery of the support or carrier. This lateral movement is imparted to the spring plate 221 and to the anvil 220 by means of curved enlargements 234, 235 on the arms m, n of the holder or presenting tool, which arms, when moved, press the plate 221 sidewise and hence move the anvil correspondingly. The arm m, of the holder or presenting tool, is carried by a lever 222 fast to the shaft 218, and the companion arm n of said tool is carried by a lever 223 that is pivoted on the shaft 218, but preferably connected therewith by a spring 224 that is fast to and coiled about said shaft and has its free end bearing against the rear side of said lever 223, which lever 223 is held in its appropriate relation to the lever 222, by the action of this spring constantly pressing it against a stop plate 225 attached to the lever 222, by which construction said arm n will be moved outwardly by said shaft concerted with the like movement of the arm m, but may be moved inwardly independently of it. These arms m, n have their inner faces or sides grooved to provide for the reception and guidance of the staple legs, and the extremity of the arm m is beveled or otherwise fashioned into a cutter as t which co-acts with the edge u of the rim of the carrier at one side of the recess cut through said rim, the cutter t acting to sever the wire as it forces it against the edge u. The shaft 218 is rocked to swing the arms m, n to and from the periphery of the carrier B by means of a rock arm 225, the bowl or stud upon the end of which travels in the path of a cam 226 fixed by a bracket 227, to the framework. The staple inserting tool or driver 219 is carried by a lever 229 that turns upon the shaft 218, which lever has a laterally project-

ing stud 230 that enters into the path of a cam 231 fixed by a bracket 232 to the framework. This lever 229 has its free end bent inward to properly position the driver 219 and the 5 sides of the latter are suitably shaped to enable them to play in the inner side grooves of the arms *m*, *n*, and it, like them, has a movement in a direction slightly tangential to the periphery of the carrier or support *B*. The 10 arms *m*, *n* of the staple holding or presenting tool also perform the function of staple leg bending arms, in coaction with the anvil 220, as will presently appear, one of them, *m*, being also made to act as a cutter, as has been 15 stated. The normal position of the parts being as shown in Fig. 57, it will be apparent that wire from a supply reel will, by a suitable rotation of the feed rollers 208, 209, be appropriately fed onward into the channel 213, and, being forced through the laterally bent channel in the guide block 212, will be carried into the circular groove 211 in the rim of the carrier and be held in said groove by the inner face of the guide plate 215. Thus 20 25 entered and guided in the groove 211 the forward end of the wire will be entered between the inner surface of the forming anvil 220 and the face of the driver 219, which latter may, if desired, be grooved to so guide it. As 30 the interior surface of the anvil 220 forms a continuation of the outer wall of the groove 211, the path of cam 231 will preferably be shaped so as to normally hold the face (or the groove therein), of the driver 219 in a position to form a continuation of the inner wall of said groove 211. As soon as the staple forming devices or mechanisms have reached a proper position in their rotative travel, this 35 driver 219 may, if desired, be slightly moved 40 outward by a suitable shape of the cam 231 and thus gently clamp the wire against the under side of the anvil 220, the cam 231 being so shaped as to immediately thereafter act upon the rock arm 225 and move the arms 45 *m*, *n*, of the holder or presenting tool outward, at which time they may act as bending arms. The cutter *t* on the arm *m* will then first bear 50 against the wire and force the same against the edge *u* of the rim of the carrier and sever the wire, thus detaching a length suitable for 55 the formation of a staple. The ends and faces of the arms *m*, *n*, will about simultaneously bear against those portions of the wire length that extend each side of the anvil 220 and 60 operate to bend the same outwardly against the sides of said anvil, as in Fig. 58, thus forming outwardly extending legs which will lie in the grooves in the inner faces of said arms *m*, *n*. When this is accomplished, the cam 65 226 causes the driver 219 to take up its outward movement and to advance concertedly with the arms *m*, *n*, and, as the concerted outward movement of the driver and arms is made, the cam like projections 234, 235 on the latter will press upon and laterally displace the anvil 220 by bearing against its retaining 70 75 spring plate 221, thus permitting the crown of the staple and the driver 219 behind it to move past the anvil at one side thereof; and, to aid the speedy movement or lateral displacement of the anvil, its inner side may be slightly beveled, so that the staple will somewhat readily pass onto its side surface. When the staple has cleared the anvil, the driver may, if desired, be retracted as the resilient 80 action of the staple legs will hold the staple in place, and the spring seated anvil 220 may be pressed back to place by the action of spring plate 221 and rest underneath the crown of the staple. But practically, since, 85 for the perfect setting of the staple, a solid bed is desirable, it is preferred to have the cam 226 hold the driver 219 in its protruded position until the staple legs are clinched, and sometimes, it is desirable for it to have, 90 and the cam 226 may be shaped to impart, a very slight additional outward movement to the driver to aid in forcing the staple legs well home after they are bent down or while that operation is being finished. Protruded 95 in its position shown in Fig. 59, the staple will be within the embrace of the arms *m*, *n*, of the holder or presenting tool and practically stand on the periphery of the carrier with its legs standing tangentially therefrom and 100 directed at the points in the material which they are to enter, and toward the clinching groove or die 236 that is cut into the periphery of the carrier *A*, and by which they are to be clinched; in other words be properly presented in inserting position. This clinching groove 236 has its ends curved inward so as to turn the staple legs toward each other, and acts, as the carriers or supports move 105 onward concertedly with the plicated webs running between them, to gradually bend said legs, as they are protruded through the plicated webs and enter into said groove or die 236, while the staple is securely held in the arms of the holder or supporting tool, with 110 its crown then resting upon the driver 219, said groove finally acting to press the staple legs snugly down onto the webs as the point of nearest contact of the two carriers or supports is passed, which is the time when 115 the driver 219 may move slightly outward to aid such clinching. The various substitutes for this clinching groove hereinbefore described may be used in connection with the other stapling mechanisms last herein shown 120 and described. It will now be perceived that, in consequence of the distance of separation of the two arms *m*, *n*, of the holder or presenting tool, which act as sustaining supports for the staple legs while being set and clinched, 125 it may not be practical to have them move rearwardly or retract in concert, and hence it is that the arm *n* which is the first one that has contact with the periphery of the carrier *A* or the clinching device, is not only made 130 the shorter so that it may not move backward until after the staple leg it supports enters into the clinching groove or die 236, but is spring seated so that it may move backward

without affecting its companion arm m . The arm m might also be independently sprung seated so as to be pressed backward by its contact with the carrier A, or the clinching die, but since these arms m and n must be positively withdrawn within the carrier or support B so as to repeat the operations of cutting the wire, bending the same into staple form, protruding, carrying, presenting and guiding the same for insertion, it is preferable to perform the retraction of the arm m by means of the cam 226, and it is accordingly shaped to withdraw the arm m progressively so that said arm shall just clear the face of the carrier A as it approaches and moves past it. All of the stapling devices will now make their rotative circuit, and, the wire being continuously fed into the carrier B, the operations described will be repeated. The size of the carrier or support B, circumferentially relative to the length of a sheet, will, of course, determine the number of sets of stapling mechanisms required to suitably fasten the plicated sheets together, and since two staples in each sheet will ordinarily suffice, the carrier is shown as supplied with two sets of stapling mechanisms, the duplicate set being shown in dotted lines, see Fig. 55, (omitted in Fig. 57,) but it must be understood that the number of stapling mechanisms may be greater according to the bulk of the product, it being practical to make the surface of the carrier less and greater than the length of a sheet, in each case a suitable number of sets of stapling mechanisms being used and the inward feed of the wire timed accordingly. The webs, as the four shown, folded longitudinally by the longitudinal folder 194, will consist of eight plies and their doubled or binding edge will pass near to the line of travel of the stapling mechanism and thus have the staples entered through said plies parallel with and near to said edge.

While the foregoing description and the illustrations referred to, apply to the use of this longitudinal stapling mechanism in connection with one longitudinal folder, it is apparent that such a stapling mechanism may bind the plicated webs received from a number of longitudinal folders, the product of each of which may be one or a number of associated webs, and these collected plicated webs consisting of a number of associated folded webs may be united together by one stapling parallel with their common binding or folded edges. The carriers or supports A, B, might additionally be provided with cutting, or cutting and folding mechanisms, as is hereinbefore shown and described. The stapled bound webs may be carried to any suitable cutting, or to combined, or separately operating cutting and folding mechanisms of any approved construction.

A more extended description of this modification of the invention is embraced in my application, Serial No. 483,192, filed August 15,

1893, which latter more explicitly embraces the same.

A further modification of this invention is illustrated in Figs. 63 to 78 inclusive. In this modified embodiment of the invention, the cylinder or support B carries not only the staple forming, holding and inserting mechanisms, but the means for supplying wire lengths thereto. The staple forming devices are in part supported and operated by a longitudinal shaft 152, that is journaled in the heads of and near the periphery of this cylinder B, and they are in part supported by housings Q that are inserted in recesses of proper size cut into the cylinder, and they are in part embraced within recessed portions of said shaft. These housings are secured in place so that their outer faces form a continuation of the peripheral surface of the cylinder or support B, (see Figs. 66 and 71,) and they provide a guideway for the holding or presenting tool and the inserting tool or driver. This shaft 152 is rotated in proper time by a wheel 173 fast upon it at one end and geared with a toothed ring 174 surrounding the shaft and fixed to the frame, from which it results that as said shaft 152 is carried around with the cylinder, the said gearing will impart to said shaft the requisite rotary motion to properly operate the mechanisms it actuates. There will be as many sets of the staple forming, holding and inserting mechanisms as may be desired, according to the width of the material to be operated upon, three being shown as appears in Fig. 64, and these, or some of them may be made adjustable with respect to others, so that the distance between the stapling points or between adjacent staples may be varied. As these staple forming, holding and inserting mechanisms are duplicates, a description of one of them will apply to all. The housings for each of these stapling mechanisms carries a circular die consisting of an outer section 180, and an inner section 166, and two side sections 178, 179 between which is provided a curved guideway for the guidance of the staple. One side section 179 has a wire feeding slot 169, and a wire receiving recess w and the side section 178 has, extending partially through it, a wire receiving recess x , which recesses are thus separated and made long enough to limit the entrance of the wire to an extent just equal to the length required to form a staple. The inner portions of the side sections 178, 179, where the wire receiving recesses w , x cut the same, constitute stationary staple leg bending arms b , e , which operate to turn or bend the ends of the wire length at right angles to the body portion as the rotating bending anvil carries the body portion onward, and the section 179 is provided circumferentially with a recess 228 that provides a circular pathway in which travels a rotary wire cutter 167 that is fast on the shaft 152. Each stapling mechanism also has a rotary staple bending

anvil, shown as consisting of two rings (see Figs. 68 and 77) that is fast upon the shaft 152, and which are respectively provided with bearing arms 175, 176, which rotary anvil arms move on opposite sides of the inner section 165 of the circular die, (see Fig. 73) that embraces but does not move with the shaft 152, the same being held rigidly in place by a back strap 177 secured to the housing Q. (See Fig. 78.) These anvil arms 175, 176 are thus held apart a distance equal to the length of the staple to be formed and they project outward a distance about twice that of the thickness of the wire from which the staple is to be formed. The side sections 178, 179 of the circular die have cut into their inner side faces, curved recesses that face each other and in which are secured cheek pieces d, h, that project inwardly therefrom suitable distances, to provide, in conjunction with other parts, channels for the guidance of the staple legs. (See Fig. 68.) Thus these cheek pieces d, h, form inside or rear walls, the outer section 180 forms outer or front walls, the side sections 178, 179 beyond the cheek pieces d, h, form outer lateral or outside walls and the arms 175, 176, of the rotating anvil form inner lateral or inside walls, which walls together constitute curved conducting guiding channels for the staple legs; and, the outer section 180 is of a thickness that provides between its inner face and the outer face of the inner section 166, a curved guiding recess or pathway for the crown of the staple that is suited to the size of the wire used. The outer or bearing face of the inner section 166, and the co-operating inner face of the outer section 180 of the circular die, are so shaped as to form not only a curved channel or guide way for the staple crown, but one that is eccentric with the shaft 152, see Fig. 66, the outward curvature of said guide way being progressively increased in a direction toward the staple holder or presenting tool, see Figs. 66, 67, and the cheek pieces d, h, are of corresponding form, see Fig. 76, so that while the arms 175, 176 of the rotary bending anvil will force the formed staple onward, the increasing arc of its pathway formed by the cheek pieces d, h, or the inner section 166, constitutes an elevator that will carry the staple into the open end of the presenting tool. The staple receiving, presenting tool or holder, and the inserting or setting tool both reciprocate in a right line in a recess or guiding way cut through the housing Q, the same being partly formed in the side sections 178, 179 and covered by a central removable cap piece, 181 see Figs. 66, 67 and 72. The staple presenting tool or holder consists of a head having bearers 257, 261, curved to fit correspondingly shaped bearings formed in the side sections 178, 179, and from opposite sides of this head there are forwardly projecting arms 182, 183, that have their inner faces recessed to provide a channel way to receive the formed staple, and these recesses each have one side wall, that which is near-

est to the staple forming devices, curved to form, when the arms are in their rearward positions, as in Fig. 66, continuations of the 70 inner surface of the eccentric guide or pathway formed between the faces of the outer section 180 and the cheek pieces d, h; and the body of the presenting tool or holder has curved recesses 191, 192 cut in its face to provide for the unobstructed movement of the anvil arms 175, 176, past it. By this construction the formed staple, carried through the curved pathway by the arms 10, 11, of the rotary anvil, will be raised to clear said 80 arms, by the section 166 or the cheek pieces d, h, acting as an elevator and be landed in the channel way within these receiving arms 182, 183, wherein the staple will be deposited with its crown resting in front of the driver 85 172. This driver or inserting tool, reciprocates within these arms, guided in part in a way cut in the cap piece 181, and the driver as well as the staple presenting tool or holder, are concertededly moved forward at appropriate times by means of a lever 171 fast on a rock shaft 185, in the slotted free end of which lever the shank 184 of the driver 172 is pivoted (see Figs. 74, 75) and this shaft 185 which is journaled in the heads of the 90 cylinder B, is appropriately rocked at suitable intervals by means of a rock arm 186 on its outer end the stud or friction bowl of which runs on a stationary cam 170 that is secured to the fixed wheel 174. The staple 100 presenting tool or holder, which has the arms 182, 183, is attached to the lever 171 by means of two rods 187, 188 that play in ears 189, 190 projecting from the sides of the free end of said lever, its position with respect to said lever 105 being secured by means of spiral springs that encircle said rods and bear at one end against the rear of the head of the said instrument and at the other against said ears. The rotary wire cutter 167 is carried by a ring 264, 110 which is fast upon the shaft 152, and said cutter 167 projects sufficiently to cause it to intercept, at right angles thereto, the plane of the transverse wire passage 169 in the side section 179, and the arm 183 of the staple 115 presenting tool is recessed to provide a clearance for said cutter. The staple length of wire enters through the passage 169, extends past the cutter 167 and entering into the wire slots w, x, reaches across the guideways in 120 which said cutter and the arms 175, 176 of the rotary anvil move, and has its leading end abutted against the inner end of the wire passage 7, and thus portions of the wire length are provided each side of said anvil sufficient 125 for the formation of the staple legs; and, in its rotative travel, this cutter 167 co-operates with the side wall of the recess 228, where the wire passage 169 joins it, to perform the cutting operation and sever a staple length. The 130 wire g from which the staples are to be formed is wound upon spools a, c, e, supported at one end of the cylinder or support B, there being as many spools as there are staple forming

mechanisms employed. The spools are journaled in brackets and the wires from them are led about feeding rollers whose shafts are rotated by a train of gears 153, 154, 155, 156, 5 the shaft of the latter having at its opposite end a worm wheel 157 engaged with a worm 158 that is on a shaft which is geared by pinions 159, 160 with a toothed wheel 161 encircling the shaft of the cylinder or support B 10 and fast to the side frame, by which gearing said roller shafts are continuously and concertedly moved. As the wires must be brought into the same plane or common feeding line, the wires from all the spools are passed between guide rollers *v, i*, thence between rollers *i, o*, and thence between guiding rollers, *o, s*, so that the three wires enter the cylinder in a common plane, see Fig. 64, where the gears 153, 154, 155 and 156, are omitted so as to expose the rollers *v, i, o, s*, which are shown in dotted lines. Within the cylinder B there is provided a wire guide plate P in which are the grooves 162, 163, 164, that so guide and direct the wires that they all enter and are presented 25 to the wire passages and cutters of the several staple forming mechanisms at points correspondingly related to each, as in Fig. 65. It being understood that the cylinders or supports A, B are geared and driven so as to revolve in unison with the other moving parts with which the material must concertedly run, that the cylinder B carries a number of staple forming, holding or presenting, and, inserting mechanisms aligned longitudinally 30 35 in the said cylinder, and that the circumference of the cylinder is equal to the length of a sheet, and that the cylinder or support A, is provided with as many co-operating staple leg clinching devices as there are staple holding or presenting mechanisms, which clinching devices may be the shallow channels or grooves with curved ends, as shown, the operation will be as follows:—The plicated material will be fed onward between the carriers A, B, suitable staple lengths of the wires will be fed to the mechanisms carried by the cylinder B, and the wire cutting, staple forming, presenting and inserting mechanisms, will progressively act as follows:—The wire 40 45 50 55 60 65 70 will be fed through the slot or channel 169 and into the wire recesses *w, x*, or until it is stopped by abutting against the inner end of the recess *x*, whereupon a staple length of it will be cut off by the action of the rotary cutter 167. This severed wire length will immediately be intercepted or caught by the arms 175, 176 of the rotary anvil and its central body or crown portion will be carried into the guideway between the side sections 178, 179, 75 80 85 90 95 100 105 110 115 120 125 130 135 140 145 150 155 160 165 170 175 180 185 190 195 198 200 205 210 215 220 225 230 235 240 245 250 255 260 265 270 275 280 285 290 295 wheel 237 that is moved in timely unison with said carrier. The function of this feeding wheel 237 is to receive the staples from a quantity that are piled one upon another, 5 heads and points in the like direction, so as to descend by gravity in a feeding chute 233 the open bottom of which rests over said feeding wheel 237, and transport the staples in succession to the holding and inserting devices. This feeding wheel 237 is provided in its periphery at equal distances apart with carrying hooks 238 which are formed by cutting suitable recesses into the face of the wheel, the hooks 238 thus projecting sufficiently to engage and each recess being of a depth to receive but one staple, the legs of which will extend rearward along each side. This wheel, however, is made of less thickness than the distance between the staple 15 legs so as to provide spaces between them and the sides of the wheel for the entrance of the carrying arms of a staple conveyer 243 that transfer the staple to the staple holding and inserting devices. In order to insure the correct position of the staples with respect to the conveyer 243 and to the devices to which the conveyer delivers them, side guides or plates 241, 242, are arranged about a portion of the feeding wheel 102, and set apart a sufficient distance to provide staple leg spaces 20 between them and the arms of the conveyer 243. To insure the retention of the staples in the recesses of this wheel 237, a supporting guide plate 239, extends from the chute 233 to the guides 241, 242, and it is supported coincident with the periphery of the wheel 237 and may be continued to a point still nearer to the periphery of the support or carrier B, if desired. The row of staples 25 piled in the chute 233, is constantly pressed downward preferably by gravity, against the periphery of the wheel 237, and the lowermost staple will be detached and its crown caused to enter into a recess of the wheel 237, as a hook passes and its recess is brought beneath the staple, its crown being entered in front of and thus engaged by a hook 238, while its legs will extend at each side of the said wheel. Thus each lowermost staple will be detached 30 from the row of staples and be carried onward to be set, its crown being foremost and its legs trailing rearward, while the succeeding staples will be fed downward against the wheel to be similarly operated upon. Each staple 35 so detached from the row and carried onward by the rotating wheel 237 for delivery to the presenting and setting devices, is held in place for a distance by the supporting guide plate 239. As the legs of made staples tend to 40 spring apart or stand at slightly obtuse angles with respect to their crowns, it follows that as each staple is carried onward by a hook 238, its slightly expanded legs will press against the inner surfaces of the side guides 241, 242, with sufficient force to insure the 45 centering of the staple and its being moved forward in correct position up to the surface

of the carrier or support B and thus be accurately presented at the point where it is engaged by the carrying arms of the staple conveyer which deliver it to the stapling mechanisms. This carrier or support B, travels at a much greater surface speed than the feeding wheel 237, and the surface speed of the latter is such that each of its staple carrying hooks will be brought into position to deliver a staple thereto, at each revolution of the carrier or support B, when the staple receiving conveyer of the latter arrives into suitable co-operative relation thereto. The 50 staple detaching conveyer 243 is a vibrating device pivoted in one end of a swinging lever 244 and it has at its inner end a tail piece 252 that co-operates with a fixed stud 251 and its outer end is composed of two arms or plates 55 (see Fig. 81) preferably elastic, which arms are curved or hook like and are separated sufficiently to enable them to enter behind the crown of the staple, between its legs and within the side guides 241, 242, as a hook 238 of 60 the wheel 237 brings a staple within the range of action of this conveyer 243, at which time it is protruded from the surface of the cylinder B in its rotary movement therewith. The legs of the staples will be pressed against 65 the side guides 241, 242, as the wheel, with its hooks each carrying a staple, slowly approaches the periphery of the cylinder or support B, while the rapidly advancing conveyer 243 will enter within the side guides between 70 the staple legs and behind its crown, and, swinging inwardly, it will remove a staple from the co-operating hook 238, of the wheel 237, the legs of which staple, pressing against the side guides 241, 242, will trail rearward 75 and be prevented from being thrown beyond control by the sudden contact therewith of the conveyer or by its rapid detaching movement; and these side guides are extended about the periphery of cylinder B sufficiently to form a 80 continuous guide for the staple until it is delivered therefrom to the staple receiving devices of the cylinder B. The conveyer 243 should be made of two elastic arms or plates for the purpose of enabling them to adjustably move in passing between the side guides 85 241, 242 and so as to insure their entering between the staple legs. Their slight lateral contraction may be attained by making the opening in the periphery of the cylinder or support B, through which they rock, of such 90 form as to cause this slight movement at the very last part thereof, or just at the time of the extreme outward movement of the conveyer, as by a slight swell on their sides, of 95 the inner surfaces of the side guides 241, 242 which may be contracted along their edges nearest to the cylinder, carrier or support B to insure this slight movement. As soon as the staple is engaged by the conveyer 243, the rock shaft 100 245, actuated by a rock arm 247 and a cam 248, will be moved to vibrate the arm 246, which rocks the swinging lever 244 in which the conveyer 243 is pivoted, the movement be-

ing made against the pressure of a spring 254. The lever 244 thus causes the staple conveyer 243 to swing inward and bring the staple it has engaged within the cylinder or support B 5 and deposit it between two spring seated end guides 249, 250 of the staple holding presenting, inserting mechanisms. These end guides are carried by a fixed bracket and have inner faces provided with flaring slots which so 10 guide the staple that it will assume an upright position within them while held by the conveyer 243, in which upright position said staple may readily enter the channel like guide formed between the sides 258, 259 of 15 the staple holding or presenting tool and rest upon the inserting tool or driver 255, that stands in said channel like guide of said presenting tool or holder and over which driver said tool moves outward to strip the staple 20 from the embrace of the side guides 249, 250 and conveyer 243. This staple presenting tool or holder is sheath like and it moves in a hollow fixed bracket 260, and between its sides 258, 259 or within the channel like guide 25 it forms, the inserting tool or driver 255 reciprocates, said inserting tool 255 having depending actuating arms 256, 279, carrying a friction roller 303 that is embraced by the arms of a bifurcated lever 304 fast on the 30 rock shaft 245 and said presenting tool being seated upon springs 305, 306 that surround the arms 256, 279. In this operation of stripping the staple from the wheel 237, the stud 251 and curved tail piece or arm 252 of the 35 conveyer, together with the spring 253 which tends to press the conveyer forward and the spring 254 which tends to press it outward, co-operate to facilitate the holding and releasing action of these parts. The tail 252 of 40 the conveyer is so curved as to give to it, on the primary movement of the shaft 245 only the required range of outward movement that will cause said conveyer to be in correct position to engage and detach a staple from the 45 feeding wheel 237 and carry it within the carrying cylinder or support B. When, however, the staple has been brought well within the cylinder, the continued movement of shaft 245, while it will no longer move the conveyer 50 by reason of the curved end of its tail 252, the continued movement which it imparts to the lever 246, will, through its rock arm 304, press outward upon the friction roll of the actuating arms 256 of the inserting tool or 55 driver 255, and cause the same to advance, and through the springs 305, 306, carrying the holder or presenting tool 258, 259, with it. As the holder or presenting tool advances it engages the end guides 249, 250 and presses them 60 apart laterally, thus causing the staple to become embraced within the channel like guide of the holder or presenting tool, with its crown resting upon the end or face of the inserting tool or driver 255. Simultaneously with this 65 advancing movement of the holder or presenting tool, the conveyer is swung rearwardly out of the way by the traverse of the curved or hook

like arms, at its outer end, over the face of the side 258 of the staple holder, as is seen in Fig. 80. When the staple presenting tool has received the staple it continues to move outward until the staple is protruded beyond the surface of cylinder B, as in Fig. 80, its limit of movement being controlled by a suitable stop 270 which arrests its further progress, 70 and the staple inserting tool or driver 255 will thereafter act in proper time, to constitute a setting bed or driver operating to force the staple through the paper into engagement with a co-acting clinching device, such as may 75 be carried by an opposite support or co-acting cylinder, or otherwise provided as hereinbefore explained. The holder or presenting tool carrying the staple will move the staple into contact with the material to be stapled, insert the staple legs through the material and project them into the clinching device, and, under the pressure of its contact with the co-acting cylinder or the clinching die, the presenting tool will gradually retire against the 80 pressure of its supporting springs 305, 306, while the inserting tool is held stationary. The setting of the staple having been completed by the clinching of its legs, the cam actuating the lever 304 on the shaft 245 will cause all 85 the parts to assume their first described positions and the operations set forth to be repeated.

A more complete exposition of the foregoing modification will be found in my application, Serial No. 483,569, filed August 19, 1893, 100 which explicitly embraces the same.

In the modification illustrated in Figs. 86 to 95 the moving stapling mechanisms are rotative, as in all of the other embodiments 105 of this invention, although the rotative feature of this modification is embodied in oscillation. In this stapling apparatus the staple is formed, carried to and presented at the staple setting point by an oscillating holder 110 or presenting tool and is there inserted and set into the running material by means of a reciprocating inserting tool or driver, and a stationary co-operating clinching die. The oscillation of the holder is so timed that as it 115 approaches, reaches and passes the staple setting point, its direction of and speed of travel is that of the moving material through which the staple is to be inserted, and in which it is to be clinched or set. In the return movement of its oscillation this holder returns to the wire feeding mechanism, cuts off a staple length of wire, and said wire length is formed 120 into a staple and delivered within this holder ready for a repetition of the downward movement or carrying, holding or presenting, inserting or driving, and, clinching operations. The wire feeding, staple forming, holding or 125 presenting and inserting means, mechanisms, tools or devices, are all supported upon a stationary plate bracket 265 which projects from an arm 266 that is secured to the frame of a delivery apparatus, as for instance, that which supports the fold laying rolls 105, 106 through 130

which the plicated material to be stapled is fed onward for delivery, as in the preceding embodiments of this invention. The movements of the stapling mechanisms are imparted herein by means of a connecting rod 267, that is reciprocated by timely movements imparted by a cam 268 which is for convenience shown as guided upon the shaft 207 of the cylinder or carrier B, which corresponds with the similar carrier in the preceding views where said carrier is shown as containing cutting and folding mechanisms, said cam 268 being suitably shaped to give the requisite movement to the carrier or support for the staple holding or presenting, and inserting devices, instrumentalities or tools, so that their speed of onward movement at the time of the setting of the staple shall coincide with the like movement of the material in which the staple is to be set. With this preliminary statement, the operation of the mechanisms will be readily understood. The stationary plate bracket 265 is provided with a wire feeding slot 269 through which the wire is fed by means of a reciprocating clamping slide 260, that is guided in an arm 277. The wire being received from a reel, is passed through said slot, and nipped in the feeding direction by the pawl 271, carried by the slide, and held against any return movement by a pair of spring seated dogs 272, 273, the necessary reciprocatory motion being given to the slide 260 by means of a bell crank 274, and a reciprocating rod 275, a bowl attached to which runs in the slot of a vibrating cam 276, which cam swings on the shaft 207, over which shaft the rod 275 slides by means of its bifurcated end.

The stapling mechanism consists of two members that have their center of motion upon a shaft 301, so as to have a rotative movement, namely, an oscillation. One member, 280, which contains the forming anvil 281, and co-operative bending arms *q*, *z*, is shown in section in Figs. 88, 89 and 90, and has a head which is provided with a wire slot for the reception of the staple length of wire protruded through the directing slot 269 of the feed plate 265. This upper or staple forming member 280 has a downward movement, the extent of which is determined by a rest block 278 that supports said head with its wire slots aligned with the slot 269, so that the staple length of wire may be fed into said head to a distance suitable for the formation of a staple, and said member 280 is capable of rising above said block 278 a suitable distance in aid of the operation of forming a staple, as is hereinafter explained. The head of the staple forming member 280 is made hollow to a size adapted to receive, support and guide a reciprocating anvil 281, that carries on its upper side a rack 282 through which it is moved to and fro by means of a rocking segment 283 formed on the pendent end of a lever 284, which is pivoted in arms 285 fast to the anvil 281, the slotted upper end of which le-

ver 284 is controlled by a pivot 286 fixed to the plate 265. The other member 290, which is the staple holding or presenting tool, and carries the inserting tool or driver 288, is shown in Figs. 88 and 90 in section. It is hung to oscillate upon the shaft 301, and has the cam 276 attached to it. This holder 290 is capable of moving downward to or slightly beyond the staple setting point, or dotted position of it, shown in Fig. 86, and upward to a position slightly above that shown in full lines in Fig. 86. This holder or presenting tool 290, is recessed longitudinally to form holding arms *k*, *y*, the inner sides of which are provided with longitudinal slots approximately of the size of the wire from which the staple is formed, into which the staple legs of the formed staple are carried or drawn by the forming anvil, as will presently be explained. See Fig. 91. This holder 290 is also provided in its inner sides with longitudinal guide slots in which the inserting tool or driver 288 reciprocates. This inserting tool 288 is provided between the base of the holder 290 and its own rear end with a strong spring 289, preferably supported on a rod as shown, and on one side there projects from the presenting tool or driver 288 an arm 291, which engages a fixed cam plate 292 as the holder or presenting tool moves upward, and a trigger cam 293, as the holder or presenting tool moves downward. This trigger cam 293 is pivoted so as to slightly swing, it being held in its forward position against a stop 310 by means of an arm 294, attached to its shaft and borne upon by a spring 295. The oscillating movements of the holder or presenting tool are imparted thereto by means of the cam 268 through the connecting rod 267, which vibrates a two armed swinging lever, to one arm 296 of which the connecting rod is attached, and the other arm 297 of which, is connected by a link 298 with a rock arm 299 attached to the carrying stock of the holder or presenting tool. When the said holder or presenting tool 290, which transports the staple from the forming point down to the setting point, makes its upward or return movement, it will not only come in contact with the upper member or staple former 280, but lift the same from off the rest block 278 to a distance sufficient to enable the cutter 300, which is fixed to the holder or presenting tool, to sever a staple length of wire by the movement of said cutter past the wire feeding slot 269, and immediately following the cutting of the wire, as the upward concerted movement of the holder or presenting tool 290 and the member 280, is continued, the slotted arm 284, will move over the stud or pin 286 which will act to rock the segment 283 rearward, and through the rack 282, impart a like movement to the forming anvil 281, which will, in such rearward movement draw the wire length inward thereby causing the bending arms *q*, *z*, to bend the ends of the wire length at right angles to its central body portion, thereby converting the

same into a staple. This formed staple is carried bodily, by the continued movement of the anvil, into the staple holder or presenting tool, where its legs are entered into the 5 grooves in the inner faces of the holding guiding arms *k*, *y*, of said holder, while the crown or head of the staple rests against the end or face of the inserting tool 288, as seen in Fig. 90; which inserting tool 288 is then held in 10 its rearward position by means of its arm 291 bearing in contact with the cam plate 292. As the downward or return movement of the stapling tools is made, to seat the member 280 upon the rest block 278, the lever 284 will be 15 rocked to swing the segment 283 in the opposite direction and cause it to restore the forming anvil to its forward position in advance of the wire slot 269 ready to repeat the operation of forming a staple. The staple thus 20 formed is securely held in the grooves of the arms *k*, *y*, of the holder or presenting tool, and, as that tool further descends the staple will be transported. Now, while this holder 25 290 is making its downward movement, its arm 291 will pass onto the rear face of the trigger cam 293, the curvature of which will slightly but still further compress the spring 289, and when the forward end of the holder 290 has reached the setting point for the 30 staple, the arm 291 of the inserting tool or driver will pass off from the lower end of the trigger cam 293, thus releasing the spring 289, which will suddenly and with great power quickly expand to thrust the said 35 inserting tool or driver forward until it is arrested by the rear ends of the arms *k*, *y*, thus carrying before it the staple, and causing the same to be inserted into or through the material and the legs thereof to be clinched by 40 a suitable co-operating clinching mechanism, which will be hereinafter described. This setting action, will, therefore, be performed while the staple holder or presenting tool is moving in the same direction and substantially with 45 the same surface speed at which the material to be stapled is traveling, and hence be performed without injury to the moving material; and, as soon as the staple is inserted and has its legs clinched down, it will be relieved 50 from any hold by the presenting and inserting tools so that the same may be retracted or moved inwardly and upwardly while the material carrying the staple moves onward. During this downward movement of the holder or presenting tool 290, and it may be during 55 its partial return, a staple length of wire is again fed onward into the head of the upper or staple forming member 280, and when the holder 290 moves upward its arm 291 will 60 pass in front of the trigger cam 293, and making contact with the cam plate 292, will be gradually moved rearward, thereby compressing the spring 289, and, when the holder 290 comes into contact with the staple forming 65 member 280 it lifts the same, causes the cutter 300 to sever the wire length, the segment 283 to rock and draw the forming anvil

281 rearward, thus bending such wire length into staple form, and depositing the same in the grooves of the arms of the holder 290 70 with its crown or head resting in front of the driver 288.

The clinching mechanism may be of any suitable form, but as herein shown, and as is preferred, since the operation of the inserting tool or setting driver is a very rapid one, said clinching mechanism may be a simple block, having clinching die 311, as shown in Figs. 86, 94 and 95, the face of which is provided with a transverse recess, the ends of 80 which are slightly curved to cause the staple legs to bend inward or toward each other, and which recess is continued downward in the block so that the clinched staple legs may pass out of or off from the same without obstruction, and it is preferable to continue the curvature or inclination of the ends of this recess throughout the depth of the block, so that the actual clinching may be prolonged slightly to insure a perfect operation. The 85 cylinders A, B are shown by partial peripheral lines only, since they may be provided with simply cutting mechanisms, or with cutting and folding mechanisms, as hereinbefore set forth. 95

A more complete exposition of the foregoing modification will be found in my application, Serial No. 483,570, filed August 19, 1893, which explicitly embraces the same.

The various structures of stapling mechanisms herein shown and described, though designed for co-operation with fast printing machines, will be found to be well adapted to the stapling of material automatically fed to them from any other mechanism, or by 105 hand.

Although only two printing mechanisms are shown as the means for printing the web or webs which are to be severed into sheets and a number of which sheets, associated together or plicated, are to be united by stapling so as to form a bound book-like package, it is to be understood that many printing machines provided with means for plicating the same, may be employed to deliver either 110 webs or sheets to the stapling mechanisms, whereby the printed and plicated material will be bound together by staples. It is to be further understood that a web, webs or sheets, from a number of printing machines 120 may be conveyed over two or more longitudinal folders, and thus be plicated by association or folding, so as to be simultaneously acted upon and bound together by the stapling mechanisms; or a web, webs or sheets, from 125 one or more sources of supply independent of the printing of said web, webs or sheets by single or multiplex printing machines, may be plicated either by associating bars, combining rollers, or longitudinal folders, and delivered to the stapling mechanisms to be bound together as a single product, and in any of the above cases, there may be one or more supplements such as a plain or colored web, 130

webs or sheets, or a fancifully printed or ornamented web, webs or sheets, adapted to be used as an ornamental cover or advertising page or pages, which supplement or supplements 5 may be combined with the main web, webs, sheet, or sheets, as a component part of the plications, by leading the same into association therewith at any convenient point, as over the final longitudinal folder or folders, 10 or, by leading the same into association with the plicated material as it passes into the range of action of the stapling mechanism. In short, the plication of the material, whether printed in one or more printing machines, 15 upon one or both sides, in part upon one side and in part upon both sides, or received, unornamented or in any condition of ornamentation, from one or more sources of supply, may be accomplished in any suitable way. 20 Thus sheets may be collected on a cylinder, or be associated in a common pathway, or be combined at a pair of cylinders, or be plicated by folding; and, webs (or sheets conveyed in pathways the equivalent of webs), may be 25 plicated by associating bars, turning devices, combining cylinders, longitudinal folders, or by simply leading two sets into association.

In all of the illustrations of the embodiments of this invention, the transverse severing 30 of the webs into sheets is shown as performed after the web or webs have left the longitudinal folders, and been stapled. This method is adopted because of the convenience resulting from conducting the material onward in the web, but, it is obvious that this transverse cutting may be performed immediately following the last printing operation upon the web or webs, although the sheets thus formed will then require conducting pathways 35 to properly convey or direct them through the machine. Where transverse cutting is referred to therefore it is to be considered that it may be performed before, during, or after plication, or longitudinal folding, or stapling, 40 or as an operation accompanying transverse folding, being performed before, during or after such folding, whether the cutting devices are supported in the folding blade carrier, or otherwise.

The transverse folding is shown or described as accomplished in an apparatus in which the stapling mechanisms are embodied, and although this is highly advantageous it may be performed quite independently thereof, by 45 simply providing means for conducting the staple bound sheets in succession to any folding machine, or the stapled bound material in web form might be conducted to a combined cutting and folding machine, or first to 50 a cutting and then to a folding machine.

It will of course be obvious that the stapling mechanisms may be one set or a number of sets as may be desired. Where the support for the stapling devices is a cylinder, 55 as shown in some of the figures of the drawings, there will be as many sets of stapling mechanisms, as may be required according to

the size of the cylinder carrier or support therefor; but the size of the cylinder will be equal to, less, or greater, than the length of 70 the sheet, according to its speed of movement relative to that of the material the same being suited to the appropriate stapling of the sheet to be operated upon; and when the machine is capacitated to produce sheets of different sizes, as it may be, the stapling mechanisms may be adapted for adjustment to suit the situation required by such changes. In stapling upon a line transverse to the run of the material, it will be found advantageous 80 where a change in the size of the product is provided for, to have one or more of the stapling mechanisms adjustable laterally.

Although in the embodiments of the improvements herein shown, a primary longitudinal folder or folders are provided for, it will be readily apparent that, although this is advantageous for many reasons, it is not an essential characteristic, since the webs or sheets may be stapled together on their ultimate binding line before any folding operation is performed upon them, or after they have been one or more times folded, as by a rotating folding machine, so long as one fold is imparted to them in, on, or near, the stapled line of union or binding.

The preferred mode of bending the staple legs to clinch them, is that commonly practiced, and it has, therefore, been adopted in the principal illustrations of this invention; 100 but any of the clinching mechanisms herein described may so perform the clinching operation as to bend the legs of the staple toward each other, as in the principal illustrations, or they may so operate as to bend said 105 legs in opposite directions or away from each other, or, to bend both of the legs in the same or any desired direction. By using staples having but one leg that protrudes beyond the pack or plies through which it is inserted, 110 the clinching operation might be so performed by bending said leg parallel with the head of the staple, and in the same or a contrary direction, thereto, or otherwise. The swinging anvil 115 46 might detach a wire length from a suitable holder and convert it into a staple as it moves into the carrier or support B by bending the ends of the wire at right angles to its body portion, thus forming the legs between the sides of the anvil and the walls 74, 120 75 of the recess in the carrier or support B; and, the nib 3 of this anvil may be replaced by a slight recess in or near the end of the swinging anvil, and even this, as well as the nib, may be omitted, since neither is essential 125 though advantageous in the rapid working of some of the mechanisms. The guard 43 is not requisite to the successful carriage of the staple length of wire from the point at which it is cut from the body of the wire to that at which it is acted upon in forming it into a staple, but this guard may act to insure a steady presentation of the wire for and during cutting, and certainty in the transfer

movement of the staple length of wire without said wire being bent or worked out of place.

It is practical to allow the staple legs to project considerably beyond the arms of the holder, as in Figs. 41, 52, 59, and thus provide for a very short movement of said arms.

The carriers A, B, C, which have been referred to, serve principally as supports for the devices, tools or instrumentalities they carry, and the cylinder form of them has been stated to be preferred, but it is to be understood that when they serve as such supports only, they need not be cylinders, but if it is desired to utilize any portion of their peripheries, then such portions may be retained, and so far as this invention is concerned, only such portions of them as are necessary to afford support for the stapling mechanisms need be present; but, it will be apparent that when these carriers or supports are in cylinder form they may well act as the means for moving the material past the stapling mechanisms, as they will operate as carriers whenever the material is so fed to them that it is held upon one or the other or nipped between them. In this case the material need not pass between the feeding rollers, as herein shown. By thus giving the support for the stapling mechanisms the form of a cylinder, said cylinder may also act to collect many sheets upon its surface before the same are stapled.

It is to be observed from the foregoing description that the staple inserting means consist generally of a staple holder or presenting tool which holds or presents and sometimes guides the made staple so that its legs shall properly enter the material, and a tool or driver which acts to compel the entrance of the staple into the material. It is to be understood, however, that the staple holding or presenting tool may also act as a tool or driver for inserting the staple into the material to be stapled.

By the term "independent means," as used in the claims, is meant means additional to the staple holder or presenting tool and which act to feed plicated webs or sheets when the staple holder or presenting tool is not in the position where the staple is to be inserted into such webs or sheets.

In some forms of construction herein shown and described, one device *per se* performs more than a single function, as for instance, one of the conveyer arms 44, 45 may act as a wire cutter as well as a conveying arm, and said conveying arms may also act as bending arms constituting one member of the staple forming mechanism. Again as before stated the staple holding device which holds or presents the staple may also act as the means for inserting the same into the material to be stapled. It is therefore to be understood that in carrying out this invention, the constructor is at liberty to make any one single device to perform one, two or more functions as he sees fit; also, that in this specification where any

single device is particularly referred to it is to be understood to be the device which is characterized by the function it then performs, although that function may be but one of its many functions.

The various modifications of this invention which are shown in Figs. 34 to 95 and hereinbefore described, are introduced herein to exemplify, illustrate and assist in explaining the broad scope of the claims, and such modifications are therefore to be taken as included herein only so far as they are broadly comprehended in the claims; in all other respects they are reserved as the subject-matter of separate applications.

What therefore is claimed is—

1. The combination, substantially as described, of independent means for feeding plicated webs or sheets onward past staple inserting means, and staple inserting means operating to insert a staple through the moving webs or sheets.

2. The combination, substantially as described, of independent means for feeding plicated webs or sheets onward past staple inserting means, and staple inserting and clinching means operating to insert a staple through the moving webs or sheets and clinch its legs.

3. The combination, substantially as described, of means for feeding plicated webs or sheets continuously onward past staple inserting means, and staple inserting means operating to insert a staple through the webs or sheets.

4. The combination, substantially as described, of means for feeding plicated webs or sheets continuously onward past staple inserting means, and staple inserting and clinching means operating to insert a staple through the webs or sheets and clinch its legs.

5. The combination, substantially as described, of a mechanism for printing the material, means for plicating the same, means for feeding the plicated material onward past staple inserting means, and, staple inserting means operating to insert a staple through the moving material.

6. The combination, substantially as described, of a mechanism for printing the material, means for plicating the same, means for feeding the plicated material onward past staple inserting means, and, staple inserting and clinching means operating to insert a staple through the moving material, and clinch its legs.

7. The combination, substantially as described, of a mechanism for printing the material, means for plicating the same, means for feeding the plicated material onward past staple inserting means, staple inserting and clinching means operating to insert a staple through the moving material and clinch its legs, and, mechanism operating to double or fold the stapled material in, on, or near, its line of union.

8. The combination, substantially as de-

scribed, of a means for printing a web or webs of material, means for plicating the same, means for feeding the plicated material onward past staple inserting means, staple inserting and clinching means operating to insert a staple through the moving material and clinch its legs, and, cutting devices severing the material transversely into sheet lengths.

9. The combination, substantially as described, of a mechanism for printing a web or webs of material, means for plicating the same, means for feeding the plicated material onward past staple inserting means, staple inserting and clinching means operating to insert a staple through the moving material and clinch its legs, cutting devices severing the material transversely into sheet lengths, and, mechanism operating to double or fold the stapled material in, on, or near, its line of union.

10. The combination, substantially as described, of means for plicating material, independent means for feeding the material onward past staple inserting means, and staple inserting means operating to insert a staple through the moving material.

11. The combination, substantially as described, of means for plicating material, independent means for feeding the material onward past staple inserting means, and staple inserting and clinching means operating to insert a staple through the moving material and clinch its legs.

12. The combination, substantially as described, of means for plicating material, means for feeding the material onward past staple inserting means, staple inserting and clinching means operating to insert a staple through the moving material and clinch its legs, and, mechanism operating to double or fold the stapled material in, on, or near, its line of union.

13. The combination, substantially as described, of means for plicating a web or webs of material, independent means for feeding the material onward past staple inserting means, staple inserting and clinching means operating to insert a staple through the moving material and clinch its legs, and, cutting devices severing the material transversely into sheet lengths.

14. The combination, substantially as described, of means for plicating a web or webs of material, means for feeding the material onward past staple inserting means, staple inserting and clinching means operating to insert a staple through the moving material and clinch its legs, cutting devices severing the material transversely into sheet lengths, and, mechanism, operating to double or fold the stapled material in, on, or near, its line of union.

15. The combination, substantially as described, of a mechanism for printing the material, a longitudinal folder plicating the same, means for feeding the plicated material onward past staple inserting means, and staple

inserting means operating to insert a staple through the moving material.

16. The combination, substantially as described, of a mechanism for printing the material, a longitudinal folder plicating the same, means for feeding the plicated material onward past staple inserting means, and staple inserting and clinching means operating to insert a staple through the moving material and clinch its legs.

17. The combination, substantially as described, of a mechanism for printing a web or webs of material a longitudinal folder pli- 80 cating the same, means for feeding the pli- cated material onward past staple inserting means, staple inserting and clinching means operating to insert a staple through the moving material and clinch its legs, and, cutting 85 devices severing the material transversely into sheet lengths.

18. The combination, substantially as described, of a mechanism for printing a web or webs of material a longitudinal folder pli- 90 cating the same, means for feeding the pli- cated material onward past staple inserting means, staple inserting and clinching means operating to insert a staple through the moving material and clinch its legs, cutting de- 95 vices severing the material transversely into sheet lengths, and, mechanism operating to double or fold the stapled material in, on, or near, its line of union.

19. The combination, substantially as described, of a mechanism for printing the material, a longitudinal folder plicating the same, a slitter dividing the material longitudinally, means for feeding the plicated material onward past staple inserting means, and, staple 105 inserting and clinching means operating to insert a staple through the moving material and clinch its legs.

20. The combination, substantially as described, of a printing mechanism for printing a web or webs, a longitudinal folder plicating the same, a slitter dividing the web or webs longitudinally, means for feeding the plicated web or webs onward past staple inserting means, staple inserting and clinching means 115 operating to insert a staple through the moving material and clinch its legs, and, a cutting mechanism operating to sever the stapled material transversely into sheet lengths.

21. The combination, substantially as described, of a printing mechanism for printing a web or webs, a longitudinal folder plicating the same, a slitter dividing the web or webs longitudinally, means for feeding the plicated web or webs onward past staple inserting 125 means, staple inserting and clinching means operating to insert a staple through the moving material and clinch its legs, a cutting mechanism operating to sever the stapled material transversely into sheet lengths, and, a 130 mechanism operating to double or fold the stapled material in, on, or near, its line of union.

22. The combination, substantially as de-

- scribed, of a mechanism for printing and delivering two or more webs or sheets, means for associating said webs or sheets, a longitudinal folder plicating the same, means for feeding the plicated material onward past staple inserting means, and staple inserting and clinching means operating to insert a staple through the moving material and clinch its legs.
23. The combination, substantially as described, of a mechanism for printing and delivering two or more webs, means for associating said webs, a longitudinal folder plicating the same, means for feeding the plicated material onward past staple inserting means, staple inserting and clinching means operating to insert a staple through the moving material and clinch its legs, and, a cutting mechanism operating to sever the stapled material transversely into sheet lengths.
24. The combination, substantially as described, of a mechanism for printing or delivering two or more webs, means for associating said webs, a longitudinal folder plicating the same, means for feeding the plicated material onward past staple inserting means, staple inserting and clinching means operating to insert a staple through the moving material and clinch its legs, a cutting mechanism operating to sever the webs into sheet lengths, and, mechanism operating to double or fold the stapled material in, on, or near, its line of union.
25. The combination of means for feeding plicated webs or sheets, with a staple holding device moving in the direction of the travel of the material to be stapled while carrying and presenting the staple into position relative to the material for its insertion therein, substantially as described.
26. The combination of means for feeding plicated webs or sheets, with a staple holding device moving in the direction of the travel of the material to be stapled while carrying and presenting the staple into position relative to the material for its insertion therein, and a tool or driver for inserting the staple therein, substantially as described.
27. In a stapling mechanism, a staple holding device moving in the direction of the travel of the material to be stapled while carrying and presenting the staple into position relative to the material for its insertion therein, and a staple leg clinching device, substantially as described.
28. In a stapling mechanism, a staple holding device moving in the direction of the travel of the material to be stapled while carrying and presenting the staple into position relative to the material for its insertion therein, a tool or driver for inserting the staple therein, and a staple leg clinching device, substantially as described.
29. In a stapling mechanism, a staple holding device moving in the direction of the travel of the material to be stapled while the staple is being carried into position to be inserted, a tool or driver for inserting the staple therein, and means feeding plicated webs or sheets continuously onward with relation thereto, substantially as described.
30. In a stapling mechanism, a staple holding device moving in the direction of the travel of the material to be stapled while carrying and presenting the staple into position relative to the material for its insertion therein, a tool or driver for inserting the staple therein, a staple leg clinching device, and means feeding the material onward with relation thereto, substantially as described.
31. In a stapling mechanism, staple inserting means moving in the direction of the travel of the material to be stapled while carrying and presenting the staple into position relative to the material for its insertion therein, substantially as described.
32. In a stapling mechanism, staple inserting means, and a staple leg clinching device, all moving in the direction of the travel of the material to be stapled while the staple is being carried into position to be presented, inserted and clinched, substantially as described.
33. In a stapling mechanism, staple inserting means, moving in the direction of the travel of the material to be stapled while carrying and presenting the staple into position relative to the material for its insertion therein, and a staple leg clinching device, substantially as described.
34. In a stapling mechanism, staple inserting means moving in the direction of the travel of the material to be stapled while carrying and presenting the staple into position relative to the material for its insertion therein, and means feeding the material onward with relation thereto, substantially as described.
35. In a stapling mechanism, staple inserting means moving in the direction of the travel of the material to be stapled while carrying and presenting the staple into position relative to the material for its insertion therein, a staple leg clinching device, and means feeding the material onward with relation thereto, substantially as described.
36. In a stapling mechanism, the combination, substantially as described, of staple inserting means, and a staple leg clinching device, all moving in the direction of the travel of the material to be stapled while the staple is being carried into position to be presented, inserted and clinched, and means feeding the material onward with relation thereto.
37. In a stapling mechanism, the combination, substantially as described, of a staple holding device moving in the direction of the travel of the material to be stapled while carrying and presenting the staple into position relative to the material for its insertion therein, a staple inserting device, and cutting devices severing the material into sheet lengths.
38. In a stapling and folding mechanism, the combination, substantially as described,

of a staple holding device moving in the direction of the travel of the material to be stapled while carrying the staple into position for insertion therein, a staple inserting device, and mechanism operating to double or fold the stapled material in, on, or near, its line of union.

39. In a stapling and folding mechanism, the combination, substantially as described, of a staple holding device moving in the direction of the travel of the material to be stapled while carrying the staple into position for insertion therein, a staple inserting device, cutting devices severing the material into sheet lengths, and mechanisms operating to double or fold the stapled material in, on, or near, its line of union.

40. In a stapling and folding mechanism, the combination, substantially as described, of a staple holding device and a staple leg clinching device both moving in the direction of the travel of the material to be stapled while the staple is being carried into position for insertion therein, means feeding the material onward past said devices, and mechanism operating to double or fold the stapled material in, on, or near, its line of union.

41. In a stapling and folding mechanism, the combination, substantially as described, of a staple holding device and a staple leg clinching device both moving in the direction of the travel of the material to be stapled while the staple is being carried into position for insertion therein, means feeding a web or webs onward past said devices, cutting mechanism operating to sever the material into sheet lengths, and mechanism operating to double or fold the stapled material in, on, or near, its line of union.

42. In a stapling and folding mechanism, the combination, substantially as described, of staple inserting means moving in the direction of the travel of the material to be stapled while the staple is being carried into position for insertion therein, a staple leg clinching device, means for feeding the material onward past said devices, and mechanism operating to double or fold the stapled material in, on, or near, its line of union.

43. In a stapling and folding mechanism, the combination substantially as described, of staple inserting means moving in the direction of the travel of the material to be stapled while the staple is being carried into position for insertion therein, a staple leg clinching device, means for feeding a web or webs onward past said devices, cutting devices severing the material into sheet lengths, and mechanism operating to double or fold the stapled material in, on, or near its line of union.

44. In a stapling mechanism, the combination, substantially as described, of independent means for feeding plicated webs or sheets, with a staple holding device moving onward with the material while the staple is being inserted therein.

45. In a stapling mechanism, the combination, substantially as described, of independent means for feeding plicated webs or sheets, a staple holding device moving onward with the material while the staple is being inserted therein, and, a tool or driver for inserting the staple therein.

46. In a stapling mechanism, the combination, substantially as described, of independent means for feeding plicated webs or sheets, a staple holding device moving onward with the material while the staple is being inserted therein, and, a staple leg clinching device.

47. In a stapling mechanism, the combination, substantially as described, of independent means for feeding plicated webs or sheets, a staple holding device moving onward with the material, a tool or driver for inserting the staple therein, and, a staple leg clinching device.

48. In a stapling mechanism, the combination, substantially as described, of a staple holding device moving onward with the material to be stapled, a staple inserting device, and means feeding the material continuously onward past said devices.

49. In a stapling mechanism, the combination, substantially as described, of a staple holding device moving onward with the material to be stapled, a staple inserting device, a staple leg clinching device, and means feeding the material continuously onward past said devices.

50. In a stapling mechanism, the combination, substantially as described, of independent means for feeding plicated webs or sheets, and staple inserting means moving onward with the material while the staple is being inserted therein.

51. In a stapling mechanism, the combination, substantially as described, of staple inserting means, and a staple leg clinching device, all moving onward with the material to be stapled while the staple is being carried into position to be presented, inserted and clinched.

52. In a stapling mechanism, the combination, substantially as described, of independent means for feeding plicated webs or sheets, staple inserting means moving onward with the material while the staple is being presented and inserted, and a staple leg clinching device.

53. In a stapling mechanism, the combination, substantially as described, of staple inserting means moving onward with the material to be stapled, and means feeding the material continuously onward past said staple inserting means.

54. In a stapling mechanism, the combination, substantially as described, of staple inserting means moving onward with the material to be stapled, means feeding the material continuously onward past said staple inserting means, and a staple leg clinching device.

55. In a stapling mechanism, the combina-

- tion, substantially as described, of staple inserting means, a staple leg clinching device, all moving onward with the material to be stapled, and means feeding the material onward past the staple inserting means.
56. In a stapling mechanism, the combination, substantially as described, of independent means for feeding plicated webs or sheets, a staple holding device moving onward with the material to be stapled, a staple inserting device, and cutting devices severing the material into sheet lengths.
57. In a stapling and folding mechanism, the combination, substantially as described, of a staple holding device moving onward with the material to be stapled, a staple inserting device, and mechanism operating to double or fold the stapled material in, on, or near, its line of union.
58. In a stapling and folding mechanism, the combination, substantially as described, of a staple holding device moving onward with the material to be stapled, a staple inserting device, cutting devices severing the material into sheet lengths, and mechanism operating to double or fold the stapled material in, on, or near, its line of union.
59. In a stapling and folding mechanism, the combination, substantially as described, of a staple holding and a staple leg clinching device both moving onward with the material to be stapled, means feeding the material onward past said devices, and mechanism operating to double or fold the stapled material in, on, or near, its line of union.
60. In a stapling and folding mechanism, the combination, substantially as described, of a staple holding and a staple leg clinching device both moving onward with the material to be stapled, means for feeding a web or webs onward past said devices, cutting mechanism operating to sever the material transversely into sheet lengths, and mechanism operating to double or fold the stapled material in, on, or near, its line of union.
61. In a stapling and folding mechanism, the combination, substantially as described, of staple inserting means moving onward with the material to be stapled, a staple leg clinching device, means for feeding the material onward past said devices, and mechanism operating to double or fold the stapled material in, on, or near, its line of union.
62. In a stapling and folding mechanism, the combination, substantially as described, of staple inserting means moving onward with the material to be stapled, a staple leg clinching device, means for feeding the material onward past said devices, cutting devices severing the material into sheet lengths, and mechanism operating to double or fold the stapled material in, on, or near, its line of union.
63. In a stapling mechanism, the combination substantially as described, of independent means for feeding plicated webs or sheets with a staple holding device moving rotatively with the material to be stapled while the staple is being inserted while the staple is being inserted therein.
64. In a stapling mechanism, the combination, substantially as described, of independent means for feeding plicated webs or sheets, a staple holding device moving rotatively with the material to be stapled while the staple is being inserted, and a tool or driver for inserting the staple therein.
65. In a stapling mechanism, the combination, substantially as described, of independent means for feeding plicated webs or sheets, a staple holding device moving rotatively with the material to be stapled while the staple is being inserted therein, and a staple leg clinching device.
66. In a stapling mechanism, the combination, substantially as described, of independent means for feeding plicated webs or sheets, a staple holding device moving rotatively with the material to be stapled, a tool or driver for inserting the staple therein, and a staple leg clinching device.
67. In a stapling mechanism, the combination, substantially as described, of a staple holding device moving rotatively with the material to be stapled while the staple is being inserted therein, a staple inserting device, and means feeding the material continuously onward past said devices.
68. In a stapling mechanism, the combination, substantially as described, of a staple holding device moving rotatively with the material to be stapled, a staple inserting device, a staple leg clinching device, and means for feeding the material continuously onward past said devices.
69. In a stapling mechanism, the combination, substantially as described, of independent means for feeding plicated webs or sheets, and staple inserting means moving rotatively with the material to be stapled while the staple is being presented and inserted.
70. In a stapling mechanism, the combination, substantially as described, of staple inserting means, and a staple leg clinching device, all moving rotatively with the material to be stapled.
71. In a stapling mechanism, the combination, substantially as described, of independent means for feeding plicated webs or sheets, staple inserting means moving rotatively with the material to be stapled while the staple is being presented and inserted, and a staple leg clinching device.
72. In a stapling mechanism, the combination, substantially as described, of staple inserting means moving rotatively with the material to be stapled and means for feeding the material continuously onward past said staple inserting means.
73. In a stapling mechanism, the combination substantially as described, of staple inserting means moving rotatively with the material to be stapled, means for feeding the material continuously onward past said staple

inserting means, and a staple leg clinching device.

74. In a stapling mechanism, the combination, substantially as described, of staple inserting means, a staple leg clinching device, all moving rotatively with the material to be stapled, and means feeding the material onward past the staple inserting means.

75. In a stapling mechanism, the combination, substantially as described, of independent means for feeding plicated webs or sheets, a staple holding device moving rotatively with the material to be stapled, a staple inserting device, and cutting devices severing the material into sheet lengths.

76. In a stapling and folding mechanism, the combination, substantially as described, of a staple holding device moving rotatively with the material to be stapled, a staple inserting device, and mechanism operating to double or fold the stapled material in, on, or near, its line of union.

77. In a stapling and folding mechanism, the combination, substantially as described, of a staple holding device moving rotatively with the material to be stapled, a staple inserting device, cutting devices severing the material into sheet lengths, and mechanism operating to double or fold the stapled material in, on, or near, its line of union.

78. In a stapling and folding mechanism, the combination, substantially as described, of a staple holding and a staple leg clinching device both moving rotatively with the material to be stapled, means for feeding the material onward past said devices, and mechanism operating to double or fold the stapled material in, on, or near, its line of union.

79. In a stapling and folding mechanism, the combination, substantially as described, of a staple holding and a staple leg clinching device both moving rotatively with the material to be stapled, means for feeding a web or webs onward past said devices, a cutting mechanism operating to sever the material transversely into sheet lengths, and mechanism operating to double or fold the stapled material in, on, or near, its line of union.

80. In a stapling and folding mechanism, the combination, substantially as described, of staple inserting means moving rotatively with the material to be stapled, a staple leg clinching device, means for feeding the material onward past said devices, and mechanism operating to double or fold the stapled material in, on, or near, its line of union.

81. In a stapling and folding mechanism, the combination, substantially as described, of staple inserting means moving rotatively with the material to be stapled, a staple leg clinching device, means for feeding the material onward past said devices, cutting devices severing the material into sheet lengths, and mechanism operating to double or fold each stapled sheet in, on, or near, its line of union.

82. The combination, substantially as described, of means for automatically feeding

plicated material onward past staple inserting means, staple inserting and clinching means operating to insert a staple through the moving material and clinch its legs, and mechanism operating to double or fold the stapled material in, on, or near, its line of union.

83. The combination, substantially as described, of means for automatically feeding plicated material onward past staple inserting means, staple inserting and clinching means operating to insert a staple through the moving material and clinch its legs, and, a rotary mechanism operating to double or fold the stapled material in, on, or near, its line of union.

84. The combination, substantially as described, of means for automatically feeding a plicated web or webs onward past staple inserting means, staple inserting and clinching means operating to insert a staple through the moving web or webs and clinch its legs, cutting devices severing the material transversely into sheet lengths, and a rotary mechanism operating to double or fold the stapled material in, on, or near, its line of union.

85. The combination, substantially as described, of a staple holding device which moves rotatively with the material to be stapled while the staple is being inserted therein, means for automatically feeding plicated material onward past the staple holding device, and, a rotating folding mechanism operating to double or fold the stapled material in, on, or near, its line of union.

86. In a stapling and folding mechanism, the combination, substantially as described, of a device operating to hold and present a staple to the material to be stapled, a device operating to clinch the legs of the staple when inserted in the material, one of which devices rotates, a folding blade carried rotatively therewith, means operating the said blade, and, devices co-operating with the folding blade to double or fold the stapled material in, on, or near, its line of union.

87. In a stapling and folding mechanism, the combination, substantially as described, of a rotating device operating to hold and present a staple to the material to be stapled, a rotating device operating to clinch the legs of the staple when inserted in the material, with one of which devices a folding blade is carried rotatively, means operating the said blade, and, devices co-operating with the folding blade to double or fold the stapled material in, on, or near, its line of union.

88. In a stapling mechanism, the combination, substantially as described, of a rotating device operating to hold and present a staple to the material to be stapled, one member of a cutting mechanism carried rotatively with said device, and a rotating device operating to clinch the legs of the staple when inserted in the material and also carrying the other member of the cutting mechanism.

89. In a stapling and folding mechanism,

- the combination, substantially as described, of a rotating device operating to hold and present a staple to the material to be stapled, one member of a cutting mechanism carried rotatively with said device, a rotating device operating to clinch the legs of the staple when inserted in the material, another member of a cutting mechanism carried rotatively with the latter device, one of said devices having a folding blade carried rotatively therewith, means operating the said blade, and devices co-operating with the folding blade to double or fold the stapled material in, on, or near, its line of union.
90. In a stapling and folding mechanism, the combination, substantially as described, of a rotative staple leg clinching device, a staple holding device, a folding blade operating in the path of rotation of the clinching device, means for operating said blade, and devices co-operating with the folding blade to double or fold the stapled material in, on, or near, its line of union.
91. In a stapling and folding mechanism, the combination, substantially as described, of a rotative staple leg clinching device, a staple holding device, a folding blade carried rotatively with the clinching device, means for operating said blade, and devices co-operating with the folding blade to double or fold the stapled material in, on, or near, its line of union.
92. In a stapling and folding mechanism, the combination, substantially as described, with staple inserting and clinching devices, of a folding blade having parts removed to enable it to pass the inserting or clinching device.
93. In a stapling and folding mechanism, the combination, substantially as described, with a rotative staple inserting means, and a staple leg clinching mechanism, of a rotative folding blade having parts removed to enable it to pass the staple inserting means or clinching mechanism.
94. In a staple forming mechanism, the combination, substantially as described, of a device provided with means for receiving a staple length of wire and operating as one member of a staple forming device, and a rotative device which is provided with the other member of the staple forming device, one of said members moving co-operatively relatively to the other in forming the staple while transferring said wire length from one member to the other.
95. In a staple forming mechanism, the combination, substantially as described, with a rotative conveyer between whose arms the staple is formed which conveyer receives, carries onward and presents a staple length of wire thereto, of a support provided with a forming anvil that moves co-operatively between said arms in forming a staple.
96. In a staple forming mechanism, the combination, substantially as described, of a device provided with means for receiving a

staple length of wire and operating as one member of a staple forming device, and a rotative device which is provided with a forming anvil that moves co-operatively relatively to said first member in forming a staple while transferring said wire length from the said first member to the rotative device.

97. In a stapling mechanism, the combination, substantially as described, of a device provided with means for receiving a staple length of wire and operating as one member of a staple forming device, a rotative device which is provided with a co-operating forming anvil that moves relatively to said member and forms the staple in transferring said wire length from the former to the latter device, and means for inserting the staple into the material.

98. In a stapling mechanism, the combination, substantially as described, with a rotative device provided with means for receiving a staple length of wire and carrying it onward thereto, and with one member of a staple forming mechanism, of a second rotative device provided with the other member of the staple forming mechanism and which co-operates with said first member to form the staple in the transfer of said wire length from one member to the other, and means for inserting the staple into the material.

99. In a stapling mechanism, the combination, substantially as described, with a rotative conveyer between whose arms the staple is formed, which conveyer receives, carries onward and presents a staple length of wire, of a device provided with a forming anvil that moves co-operatively between said arms in bending the wire into a staple, and means for inserting the staple into the material.

100. In a stapling mechanism, the combination, substantially as described, with a rotative conveyer between whose arms the staple is formed, which conveyer receives, carries onward and presents a staple length of wire, of a rotative device provided with a forming anvil that moves co-operatively between said arms in bending the wire into a staple, and means for inserting the staple into the material.

101. In a staple forming mechanism, the combination, substantially as described, with a rotative device provided with one member of a cutting mechanism for severing a staple length of wire and with means for carrying said wire length onward, of a device provided with co-operating means for forming said wire length into a staple.

102. In a staple forming mechanism, the combination, substantially as described, with a rotative conveyer provided with two arms between which the staple is formed, one of which arms operates as one member of a cutting mechanism, which conveyer receives, carries onward and presents a staple length of wire thereto, of a device provided with a forming anvil that moves co-operatively between said arms in forming the staple.

103. In a stapling mechanism, the combination, substantially as described, with a rotative device provided with one member of a cutting mechanism for severing a staple length of wire, and means for carrying said wire length onward, of a device provided with co-operating means for forming said wire length into a staple, and staple inserting means for inserting the staple into the material.
104. In a stapling mechanism, the combination, substantially as described, with a rotative conveyer provided with two arms between which the staple is formed, one of which arms operates as one member of a cutting mechanism, which conveyer receives, carries onward and presents a staple length of wire thereto, of a device provided with a forming anvil that moves co-operatively between said arms in forming the staple, and staple inserting means for inserting the staple into the material.
105. In a stapling mechanism, the combination, substantially as described, with a rotative device provided with means for receiving a staple length of wire and carrying it onward thereto, and with one member of a staple forming mechanism, of a second rotative device provided with the other member of the staple forming mechanism and which co-operates with said first member to form the staple in the transfer of said wire length from one member to the other, and staple inserting and clinching means for inserting the staple into the material and clinching its legs.
106. In a stapling mechanism, the combination, substantially as described, with a rotative conveyer between whose arms the staple is formed, which conveyer receives, carries onward and presents a staple length of wire, of a rotative device provided with a forming anvil that moves co-operatively between said arms in bending the wire into a staple, and staple inserting and clinching means for inserting the staple into the material and clinching its legs.
107. In a stapling mechanism, the combination, substantially as described, with a rotative device provided with one member of a cutting mechanism for severing a staple length of wire, and means for carrying said wire length onward, of a device provided with co-operating means for forming said wire length into a staple, and staple inserting and clinching means for inserting the staple into the material and clinching its legs.
108. In a stapling mechanism, the combination, substantially as described, with a rotative conveyer provided with two arms between which the staple is formed, one of which arms operates as one member of a cutting mechanism, which conveyer receives, carries onward and presents a staple length of wire thereto, of a device provided with a forming anvil that moves co-operatively between said arms in forming the staple, and staple inserting and clinching means for inserting the staple into the material and clinching its legs.
109. In a stapling and folding mechanism, the combination, substantially as described, of a rotating device operating to hold and present a staple to the material to be stapled and one member of a cutting mechanism carried rotatively with said device, a rotating device operating to clinch the legs of the staple when inserted in the material, another member of a cutting mechanism carried rotatively with the latter device, and a mechanism operating to double or fold the stapled material in, on, or near, its line of union.
110. In a stapling mechanism, the combination, substantially as described, of a rotative staple holding device which receives the staple at one point of its rotative travel and carries it to another point to present it for insertion in the material to be stapled, means for supplying the staples thereto at the one point, a staple leg clinching device at the other point, and means for feeding the material onward past said devices during the insertion of the staple into the moving material.
111. In a stapling mechanism, the combination, substantially as described, with a rotating staple holding device, means for supplying staples to the same at one point of its rotative travel and carrying them to another point to present them for insertion in the material to be stapled, and, one member of a cutting mechanism carried rotatively with said holding device, of a rotating staple leg clinching device and a co-operating member of the cutting mechanism carried rotatively with said clinching device.
112. In a stapling and folding mechanism, the combination, substantially as described, with a rotating staple holding device, means for supplying staples to the same at one point of its rotative travel and carrying them to another point to present them for insertion in the material to be stapled, and one member of a cutting mechanism carried rotatively with said holding device, of a rotating staple leg clinching device, a co-operating member of a cutting mechanism carried rotatively with said clinching device, and mechanism operating to double or fold the stapled material in, on, or near, its line of union.
113. In a stapling and folding mechanism, the combination, substantially as described, with a rotative conveyer between whose arms the staple is formed, which conveyer receives, carries onward and presents a staple length of wire, of a rotative device provided with a forming anvil that moves co-operatively between said arms in bending the wire into a staple, staple inserting means, a rotative staple leg clinching device, and mechanism operating to double or fold the stapled material in, on, or near, its line of union.
114. In a stapling and folding mechanism, the combination, substantially as described, with a rotative conveyer between whose arms the staple is formed, which conveyer receives, carries onward and presents a staple length of wire, of a rotative device provided with a

forming anvil that moves co-operatively between said arms in bending the wire into a staple, one member of a cutting mechanism carried rotatively with said device, staple inserting means, a rotating staple leg clinching device, a co-operating member of the cutting mechanism carried rotatively therewith, and, mechanism operating to double or fold the stapled material in, on, or near, its line of union.

115. In a staple forming mechanism, the combination, substantially as described, of a wire feeding mechanism advancing staple lengths of wire within the range of action of a cutting mechanism, a rotative conveyer operating as one member of the cutting mechanism and to carry a staple length of wire onward to the staple forming point, a member of a staple forming mechanism, and a rotative device provided with a forming anvil which operates as the other member of the staple forming mechanism.

116. In a staple forming mechanism, the combination, substantially as described, of a rotative conveyer provided with arms that receive and transport staple lengths of wire within the range of action of the staple forming mechanism, and a curved guard co-operating with said conveyer arms in transporting the wire length onward.

117. In a staple forming mechanism, the combination, substantially as described, of a rotative conveyer provided with arms that receive and transport staple lengths of wire within the range of action of the staple forming mechanism, one of which arms acts as a cutter to sever the wire, and a curved guard co-operating with said conveyer arms in cutting and transporting the wire length onward.

118. In a staple forming mechanism, the combination, substantially as described, of a wire feeding mechanism advancing staple lengths of wire within the range of action of a cutting mechanism, a rotative conveyer operating as one member of the cutting mechanism and to carry a staple length of wire onward to the staple forming point, a member of a staple forming mechanism, and a rotative device provided with a forming anvil which swings therein and operates as the other member of the staple forming mechanism.

119. In a stapling mechanism, the combination, substantially as described, of a wire feeding mechanism advancing staple lengths of wire within the range of action of a cutting mechanism, a rotative conveyer operating as one member of the cutting mechanism and to carry a staple length of wire onward to the staple forming point, a member of a staple forming mechanism, a rotative device provided with a forming anvil which swings therein and operates as the other member of the staple forming mechanism in forming the staple, transfers the staple within said rotative device, and a rocking forked guide which strips the staple from said anvil and moves it into the plane of insertion.

120. In a stapling mechanism, the combination, substantially as described, of a wire feeding mechanism advancing staple lengths of wire within the range of action of a cutting mechanism, a rotative conveyer operating as one member of the cutting mechanism and to carry a staple length of wire onward to the staple forming point, a member of a staple forming mechanism, a rotative device provided with a forming anvil which swings therein and operates as the other member of the staple forming mechanism in forming the staple, transfers the staple within said rotative device, a rocking forked guide which strips the staple from said anvil and moves it into the plane of insertion, and a staple driver.

121. In a stapling mechanism, the combination, substantially as described, of a wire feeding mechanism advancing staple lengths of wire within the range of action of a cutting mechanism, a rotative conveyer operating as one member of the cutting mechanism and to carry a staple length of wire onward to the staple forming point, a member of a staple forming mechanism, a rotative device provided with a forming anvil which swings therein and operates as the other member of the staple forming mechanism in forming the staple, transfers the staple within said rotative device, a rocking forked guide which strips the staple from said anvil and moves it into the plane of insertion, a staple driver, and a co-operating staple leg clinching device.

122. In a staple forming mechanism, the combination, substantially as described, with its co-operating member, of a moving anvil upon which the staple is formed, which anvil moves to transfer the staple into a recess in the support for said anvil, and said support having a recess the side walls of which guide the legs of the moving staple.

123. In a stapling mechanism, the combination, substantially as described, with its co-operating member, of a moving anvil upon which the staple is formed, means for moving the staple from the anvil, a moving staple driver, and a support for said anvil and driver having a recess providing side walls which guide the staple legs as the staple is moved.

124. In a staple forming mechanism the combination, substantially as described, of a swinging anvil upon which a staple is formed, and a support for said anvil provided with a recess between the side walls of which the anvil swings and the staple is guided.

125. In a stapling mechanism, the combination, substantially as described, of a swinging anvil upon which a staple is formed, a rocking forked guide by which the staple is stripped from the anvil and moved into the plane of insertion, a support for the anvil and guide, provided with a recess between the side walls of which the staple is guided as it is moved.

126. In a stapling mechanism, the combination, substantially as described, of a swinging

5 anvil upon which a staple is formed, a rocking forked guide by which the staple is stripped from the anvil and moved into the plane of insertion, a moving staple driver, a support 5 for the anvil, guide and driver, provided with a recess between the side walls of which the staple is guided as it is moved.

10 127. In a stapling mechanism, the combination, substantially as described, of staple forming devices one of which moves relatively to the other in forming a staple and brings the staple within the range of action of a stripping guide, a stripping guide operating to move the staple into the plane of insertion, and a staple driver.

15 128. In a stapling mechanism, the combination, substantially as described, of staple forming devices one of which is a swinging anvil and moves relatively to the other in forming a staple and brings the staple within the range of action of a stripping guide, a stripping guide operating to move the staple into the plane of insertion, and a staple driver.

20 129. In a stapling mechanism, the combination, substantially as described, of staple forming devices one of which is a swinging anvil and moves relatively to the other in forming a staple and brings the staple within the range of action of a stripping guide, a forked stripping guide operating to move the staple into the plane of insertion and also forms guiding surfaces for the staple when acted upon by the driver, and a staple driver.

25 130. In a stapling mechanism, the combination, substantially as described, of staple forming devices one of which moves relatively to the other in forming a staple and brings the staple within the range of action of a stripping guide, a stripping guide operating to move the staple into the plane of insertion, a staple driver, and a staple leg clinching device.

30 131. In a stapling mechanism, the combination, substantially as described, of staple forming devices one of which moves relatively to the other in forming a staple and brings the staple within the range of action of a stripping guide, a stripping guide operating to move the staple into the plane of insertion, a staple driver, and a rotating support for one of the staple forming devices, stripping guide and driver, and operating to carry the staple holding and inserting tools to the setting point.

35 132. In a stapling mechanism, the combination, substantially as described, of staple forming devices one of which moves relatively to the other in forming a staple and brings the staple within the range of action of a stripping guide, a stripping guide operating to move the staple into the plane of insertion, a staple driver, a rotative support for one of the staple forming devices, stripping guide and driver, and operating to carry the staple holding and inserting tools to the setting point,

40 and, a co-operating staple leg clinching device.

133. In a stapling mechanism, the combination, substantially as described, of staple forming devices one of which is a swinging anvil and moves relatively to the other in forming the staple and brings the staple within the range of action of a stripping guide, a stripping guide operating to move the staple into the plane of insertion and onto an internal 70 guide, and, an internal guide for the staple consisting of a rotatively moving device the construction of which is such that while it is moved with the staple as the same enters the material to be stapled its staple leg supporting parts diminish as the staple progresses into the material.

134. In a stapling mechanism, the combination, substantially as described, of staple forming devices one of which is a swinging anvil 85 and moves relatively to the other in forming the staple and brings the staple within the range of action of a stripping guide, a stripping guide operating to move the staple into the plane of insertion and onto an internal 90 guide, and, an internal guide for the staple consisting of a rotatively moving device pivoted to the anvil and the construction of which is such that while it is moved with the staple as the same enters the material to be 95 stapled its staple leg supporting parts diminish as the staple progresses into the material.

135. In a stapling mechanism, the combination, substantially as described, of staple forming devices one of which is a swinging anvil 100 and moves relatively to the other in forming the staple and brings the staple within the range of action of a stripping guide, a stripping guide operating to move the staple into 105 the plane of insertion and onto an internal guide, an internal guide for the staple consisting of a rotatively moving device the construction of which is such that while it is moved with the staple as the same enters the 110 material to be stapled its staple leg supporting parts diminish as the staple progresses into the material, and a support for the said anvil and guides provided with a recess between the side walls of which the staple is 115 guided as it is moved.

136. In a stapling mechanism, the combination, substantially as described, of staple forming devices one of which is a swinging anvil and moves relatively to the other in forming 120 the staple and brings the staple within the range of action of a stripping guide, a stripping guide operating to move the staple into the plane of insertion and onto an internal 125 guide, an internal guide for the staple consisting of a rotatively moving device the construction of which is such that while it is moved with the staple as the same enters the material to be stapled its staple leg supporting parts diminish as the staple progresses 130.

into the material, and a support for the said anvil and guides provided with a recess having side walls and ledges 64, 65 between which side walls and along which ledges the staple is guided as it is moved.

137. In a stapling mechanism, the combination, substantially as described, of staple forming devices one of which is a swinging anvil and moves relatively to the other in forming the staple and brings the staple within the range of action of a stripping guide, a stripping guide operating to move the staple into the plane of insertion and onto an internal guide, an internal guide for the staple consisting of a rotatively moving device the construction of which is such that while it is moved with the staple as the same enters the material to be stapled its staple leg supporting parts diminish as the staple progresses into the material, and a staple driver.

138. In a stapling mechanism, the combination, substantially as described, of staple forming devices one of which is a swinging anvil and moves relatively to the other in forming the staple and brings the staple within the range of action of a stripping guide, a stripping guide operating to move the staple into the plane of insertion and onto an internal guide, an internal guide for the staple consisting of a rotatively moving device the construction of which is such that while it is moved with the staple as the same enters the material to be stapled its staple leg supporting parts diminish as the staple progresses into the material, a support for the said anvil and guides provided with a recess having side walls and ledges 64, 65, between which side walls and along which ledges the staple

is guided as it is moved, and a reciprocating staple driver.

139. In a stapling mechanism, the combination, substantially as described, of staple forming devices one of which is a swinging anvil and moves relatively to the other in forming the staple and brings the staple within the range of action of a stripping guide, a stripping guide operating to move the staple into the plane of insertion and onto an internal guide, an internal guide for the staple consisting of a rotatively moving device the construction of which is such that while it is moved with the staple as the same enters the material to be stapled its staple leg supporting parts diminish as the staple progresses into the material, a support for the said anvil and guides provided with a recess having side walls and ledges 64, 65, between which side walls and along which ledges the staple is guided as it is moved, and a reciprocating staple driver. 40

140. In a stapling mechanism, the combination, substantially as described, of a mechanism for feeding wire lengths thereto, a rotating conveyer between whose arms the staple is formed, which conveyer receives, carries 45 onward and presents a staple length of wire thereto, and a support provided with a swinging forming anvil that moves co-operatively between said arms in forming the staple.

In testimony whereof I have hereunto set 50 my hand in the presence of two subscribing witnesses.

LUTHER C. CROWELL.
